CAN ARRANGING AND PACKAGING METHOD AND APPARATUS

Charles T. Walter, Markham, Ill., assignor to Continental Can Company, Inc., New York, N.Y., a corporation of New York

Application August 15, 1952, Serial No. 304,467

83 Claims. (Cl. 53—26)

The invention relates generally to the art of manufacturing cans and primarily seeks to provide a novel method of and apparatus for arranging cans in staggered and nested row and layer relation with the rows and layers in position and number for constituting a package complement, and then wrapping or bagging the can complement to form individual packages which will not only retain the cans in sanitary condition but also facilitate handling, shipping and storage thereof.

In the can manufacturing art, great progress has been made in the production of efficiently operating body-making and bottoming machinery, and cans are manufactured with great rapidity. The production of efficiently operating can handling methods and apparatus has not kept pace, and much wastage of time and labor is entailed in the handling of cans after they have been manufactured. It is commonly known that the labor cost of handling manufactured cans incidental to shipment and storage is greater than the labor cost incidental to the manufacturing of the cans. Much effort has been expended by workers in the art in attempts to develop handling methods and apparatus which will, to some extent at least, relieve this objectionable situation. One purpose has been to package groupings of cans in preformed bags, and another has been to form and seal wrappers about such can groupings or package complements. Both forms of packages have greatly facilitated the handling, shipping and storage of cans, but there remains much room for improvement in the manner and means employed in arranging the cans in the package complements and in inserting and sealing the can complements in the bags or in wrapping and sealing the can complements in order to provide a desirably rapid procedure, or both rapid procedure and packages which are compact and tight. It has been found that when the can groupings have been packaged in preformed bags, the resulting packages have been somewhat loose, although quite acceptable if formed with sufficient rapidity. It is known that by arranging the cans in staggered and nested row and layer relation, smaller, tighter and more compact packages can be formed. It is a purpose of the present invention to provide a novel method of and apparatus for arranging the cans very expeditiously in layers each composed of a plurality of rows of cans lying on their sides, and superposing layers of cans so arranged one upon another with the cans of each layer staggered and nested with relation to those of overlying or underlying layers, and then placing the whole assembled package complement of cans in a preformed bag or in position for having a wrapper formed and sealed thereabout.

Another object of the invention is to provide a novel method and apparatus of the character stated in which the cans are rolled into place on their sides in individual rows in the forming of the layers, and wherein the first rolled layer is received on a platform and the superposing of the layers is accomplished by lowering the platform a step distance corresponding approximately

to a can diameter preceding the inrolling of each succeeding layer of cans, each succeeding layer being rolled directly onto and over the last laid layer and positioned so as to bear staggered and nested relation thereto.

Another object of the invention is to provide a novel method and apparatus of the character stated in which driving conveyor pressure is applied to and over the rolling cans in order to facilitate the rolling thereof onto and over the cans of a previously laid layer and assure against upward displacement thereof.

Another object of the invention is to provide a novel method and apparatus of the character stated in which yielding pressure is applied to each can layer just prior to and as it is being lowered a step distance with the platform, thereby to overcome inertia action and prevent upward displacement of the cans.

Another object of the invention is to provide an apparatus of the character stated novel means for effecting the lowering of the platform step-by-step, said platform having an open side over which cans roll thereonto movable close to a fixed vertical can retainer wall and being equipped at its opposite side with end stops spaced vertically can layer distances apart with the stops in alternated levels each spaced a can radius farther from said open side than the remaining stops so that can layers successively rolling onto the platform and over previously laid layers and against said stops will be arranged in alternately long and short layers and in staggered and nested relation as the platform and the stops thereon are moved downwardly step-by-step to receive said layers.

Another object of the invention is to provide an apparatus of the character stated in which there are included two sets of alternately operable, vertically reciprocable gates for stopping the inrolling of cans, said gate sets being placed at the level at which the cans roll into position over the platform and being spaced apart the distance of a can radius in the direction toward the end stops which are movable with the platform so as to be disposed for cooperation with the last-named stops in staggering and nesting the successively laid can layers.

Another object of the invention is to provide in an apparatus of the character stated novel electrically controlled means for selecting the gate set which is to be lowered to stop the inrolling of cans in accordance with the level to which the platform has been lowered, thereby to assure that a long layer controlling gate set will be placed in cooperation with platform carried long layer controlling end stops or that a short layer controlling gate set will be placed in cooperation with platform carried short layer controlling end stops at each downward step position of the platform.

Another object of the invention is to provide in an apparatus of the character stated novel means for assuring against lowering of the selected can cut-off gate set and lowering of the platform until every row in the layer of cans being laid is full, said means including a set of series connected switches, each switch in which series is actuatable by the positioning of a can against a long layer controlling end stop in the particular row, and a set of similarly connected and actuatable switches operable by cans coming against the short row controlling end stops.

Another object of the invention is to provide an apparatus of the character stated, wherein the yielding pressure applied to each can layer just prior to and as it is being lowered is applied by presser members movable with the vertically reciprocable gates, said members being spring-pressed and mounted for movement in a vertical direction relative to said gates so that they can yield upwardly as they contact the cans of a layer during the lowering of the gates and then follow downwardly with

and apply yieldable pressure to said cans as they start their movement downward with the platform.

Another object of the invention is to provide an apparatus of the character stated, wherein the end stops effective to place the alternately laid short layers are shiftably mounted and are automatically retracted after they have served their function of placing the layers, and during the lowering of the platform, so that they will not interfere with shifting of the arranged package complement of cans from the platform into position for being enclosed in a bag or wrapper. 10

Another object of the invention is to provide an apparatus of the character stated, wherein a tier sheet receiving and positioning guide means is interposed uprightly between adjacent pairs of runways through which the can rows roll into place in forming the successively laid layers, each said guide means including two parallel receivers, and means being included for alternately holding tier sheets in the receivers of each pair so that a tier sheet can be inserted and held in one receiver of a pair while a tier sheet in the companion receiver of the pair is moving down step-by-step with the platform.

Another object of the invention is to provide in apparatus of the character stated, tier sheet receiving and positioning means so placed as to position a tier sheet between adjacent rows of cans and also endwise of each endmost row of cans, the two last-mentioned tier sheets preferably being heavier than the intermediate tier sheets so as to be adapted for forming end walls of a wrapped can package. 15

Another object of the invention is to provide an apparatus of the character stated, wherein the means for alternately holding and releasing tier sheets in the parallel receivers of each pair comprises a bottom vane pivotally mounted between the receivers and swingable 180° to alternately open one receiver at its bottom and close the bottom of the companion receiver, means being included for automatically shifting each said vane as the platform reaches the upper limit of its travel whereat the first laid layer of cans and the tier sheets are to be received thereon. 20

Another object of the invention is to provide an apparatus of the character stated, wherein there is included a horizontally reciprocable ram effective when the platform has been fully lowered and has a package complement of cans arranged thereon to push said can complement from the platform into position for being enclosed in the packaging paper, a second horizontally and vertically movable ram being provided and means for operating the same to first lower it into position behind the can package at the packaging station, then push the package horizontally to a sealing station, then elevate the ram and then retract it to its initial position. 25

Another object of the invention is to provide an apparatus of the character stated wherein the first and second reciprocable rams have can complement engaging heads formed of parallel spaced uprights disposed so that the uprights of one ram may interfit and pass between those of the other, making it possible for the second ram to descend behind the can complement while the first ram is in engagement therewith and move forward with the can complement with its head uprights passing through between the uprights of the first ram. 30

Another object of the invention is to provide an apparatus of the character stated, wherein the first can package complement pushing ram and the means for reciprocating the same are mounted for movement upwardly and downwardly with the platform on which the can layers are arranged, thereby to always retain the intended cooperative relation of the platform and ram. 35

Another object of the invention is to provide an apparatus of the character stated, wherein the first can complement pushing ram bears such relation to the vertically movable platform as to provide a can confining wall during the arranging of the can layers on the platform. 40

Another object of the invention is to provide in apparatus of the character stated, means for preventing elevation of the platform if the first ram is not fully retracted, and means for preventing advancing of the first ram if the platform is not at its fully lowered position. 45

Another object of the invention is to provide an apparatus of the character stated, wherein there is included means for placing a paper wrapper at the packaging station in position to be snugly applied as a tube about the package complement of cans and extend an end margin fold distance at each end beyond the cans, the second ram being offset so as to project into the end of the paper tube and against the cans therein. 50

Another object of the invention is to provide an apparatus of the character stated, wherein there is included a third ram and means for moving the same in cooperative relation to the first ram so that it will first move into close proximity to an arranged package complement of cans backed up by the first ram, then move with the first ram during the movement of the cans by said first ram to the packaging station, with the can complement engaged at its ends between and held under control by said rams. 55

Another object of the invention is to provide an apparatus of the character stated, wherein the second ram is movable into position for taking over the function of the first ram as a can package complement pushing an end supporting means so that the first ram can be retracted from its can complement contacting position, the second and third rams being offset inwardly from their carrying supports, or toward each other, so that a wrapper can be applied around the can complement and the inwardly offset ram heads in the form of a tube with marginal portions of the tube extending beyond the can complement at both ends and with the second and third rams engaging the can complement at said ends. 60

Another object of the invention is to provide an apparatus of the character stated, wherein the third ram is of a size for leaving a free space about four edges thereof, into which space the wrapper margins can be turned in completely sealing the end of the package at which the third ram is disposed. 65

Another object of the invention is to provide a method and apparatus of the character stated, wherein the third ram is movable a short distance endwise away from the end of the package which is sealed while said ram is in contact therewith, and then is lifted out of the way, thereby to avoid scraping and tearing of the wrapper at said sealed end and free the partially sealed package so that it can be discharged from the packaging station to a final sealing station. 70

Another object of the invention is to provide an apparatus of the character stated, wherein the arranged package complement of cans is received in a form at the packaging station, said form being defined by side and bottom walls composed of parallel spaced slats providing openings which permit the cans to protrude into direct contact with the packaging paper so as to provide a tight and compact package. 75

Another object of the invention is to provide an apparatus of the character stated, wherein the arranged can package complement-receiving slatted form is supported cantilever fashion at its receiving end so as to leave the other end thereof free to have a preformed bag telescoped thereover or for facilitating withdrawal or discharging therefrom of the packaged can complement, whether it be in a preformed bag or a wrapper. 80

Another object of the invention is to provide an apparatus of the character stated, wherein there is provided, at the final sealing station to which the packaged can complement is pushed by the second ram from the second or packaging station, a novel receiver which is shiftable between a horizontal position in which it receives the can package from the packaging station, and an upright position in which the other end of the package can

be sealed and the completely sealed package removed with great facility.

Another object of the invention is to provide a shiftable receiver of the character stated, which is generally U-shaped in vertical transverse section when in horizontal position and has an open end directed toward the packaging station and a closed end directed away from said station, said receiver being movable into package-receiving horizontal position before the third ram is moved out of contact with the can package, the third ram being movable upwardly out of the way after placement of the receiver in said receiving position and the second ram being then movable to discharge the partly sealed can package from the slatted form at the packaging station into said shiftable receiver.

Another object of the invention is to provide a shiftable receiver of the character stated, having its closed bottom equipped with rollers over which a finally sealed package can be rolled away with facility.

Another object of the invention is to provide a tiltable receiver of the character stated, which is also shiftable upwardly and also in a generally horizontal direction so that its open, can package-receiving end can be moved into close proximity to the delivery end of the slatted form at the packaging station in order to facilitate the pushing of the can package thereto, and then can be shifted away in a generally horizontal direction prior to full tilting of the receiver into the upright position in which the sealing of the package is completed and the package is removed from the receiver.

Another object of the invention is to provide a partially sealed package receiver of the character stated and novel means for mounting and shifting the same so that incidental to the pushing of the partially sealed can package into the receiver the marginal edge extension of the wrapper will first be cleared from the packaging station form and then the receiver will start to tilt in a manner for moving the still open end of the package clear of the offset head of the ram, thereby to permit lifting of the ram without fouling and tearing the marginal edges of the wrapper projecting beyond the cans, and to prevent the cans from falling toward the second ram as it is moved upwardly.

Another object of the invention is to provide an apparatus of the character stated, wherein the platform on which the cans are received and arranged in staggered and nested layers is lifted by fluid pressure actuated means and is lowered, step-by-step by gravity action, vertically spaced, successively removable stop means serving to control the lowering of the platform and accurately determine the successively presented levels at which the can layers are rolled onto the platform.

Another object of the invention is to provide an apparatus of the character stated, in which the platform is supported on a single column, having a long bearing slideable on said column, thus assuring that all loads and bending stresses are carried by the single support column, there being also provided a vertical guide and a fork projecting from the platform and slidably contacting said guide and serving to hold the platform against swinging about the axis of the column.

Another object of the invention is to provide an apparatus of the character stated, wherein the successively removable stop means controlling the lowering of the platform comprise stop members projecting radially from a vertical shaft into position for being selectively engageable by a projection on the platform, means being provided for moving the shaft about its axis to selectively present said stop members.

Another object of the invention is to provide an apparatus of the character stated, in which the shaft-carried stops are arranged in two vertically aligned columns spaced circumferentially about the shaft and with vertically alternated stops arranged in distinct columns

so that the stops can be successively and effectively presented for stopping and supporting the platform falling by gravity by oscillating the shaft back and forth to effectively place first one stop in one column and then the next stop in the other column, and so on.

Another object of the invention is to provide in apparatus of the character stated, means for lowering the platform step-by-step by gravity action, and air cylinder means for cushioning each lowering step of the platform.

Another object of the invention is to provide an apparatus of the character stated, wherein the long and short layer cut-off gates are air-pressure cylinder operated under control of the series-connected long and short row end stop associated switches so that the gates cannot be operated unless all rows in the long or short layers are full, the oscillatable platform drop-control shaft also being air-pressure cylinder operated under control of switch means actuated incidental to the gate movement so that lowering of the platform cannot precede proper closing of the long or short gates.

Another object of the invention is to provide an apparatus of the character stated, wherein the motion imparted to the layer cut-off gates is imparted from the controlling air pressure cylinders through crank arms, and wherein the series-connected long and short row end stop associated switches are connected in circuit with other control switch means actuated by said crank arms during the last portion of the movement thereof effective to lower the proper gates so that the lowering of the gates and discontinuance of the running in of cans is certain to precede the lowering of the platform.

Another object of the invention is to provide an apparatus of the character stated, in which the controls for the layer cut-off gates include a switch closed by depression of the oscillatable stop shaft by weight of the platform on a supporting stop, said switch being opened each time the shaft is relieved of platform pressure and by spring pressure upward on the shaft.

Another object of the invention is to provide an apparatus of the character stated, wherein, the oscillatable shaft-carried platform lowering stops are so spaced as to drop the platform through approximately equidistant steps incidental to the arranging of successive layers thereon, and then a longer step drop after the laying of the last layer of the package complement of cans into position for placing the cans for discharge from the platform to the packaging station, means being included for assuring that a long layer of cans will be laid at the commencement and also at the conclusion of each can package complement arranging cycle.

Another object of the invention is to provide an apparatus of the character stated, wherein the means for assuring that a long layer of cans will be laid at the commencement and also at the conclusion of each can package complement arranging cycle includes electrically controlled means for oscillating the platform drop stop shaft, wherein is included a phasing switch operable on the last, long drop of the platform to bring about a turning of the shaft into proper phase position should the platform, for any reason, be lowered the last long drop with the shaft in improper phase position.

Another object of the invention is to provide an apparatus of the character stated, wherein are provided a can arranging station, a can packaging station to which an arranged package complement of cans is pushed by a reciprocable ram and at which the placing of the packaging paper about the cans takes place together with a partial sealing of the package, and a final sealing station to which the package is pushed by another reciprocable ram, and means for automatically controlling the arranging of the cans so that the wrapping and sealing of a package of cans can be in progress while another

package complement of cans is being assembled and arranged.

Another object of the invention is to provide an apparatus of the character stated, wherein the control means includes a manually operable switch effective to initiate action of the ram effective to push the arranged package complement of cans to the packaging station, switch means actuated by ram travel as the ram reaches the packaging station to bring about a retraction of the ram, and control devices effective as the ram is fully retracted to discontinue the ram movement and start the platform on its upward travel in preparation for another loading cycle, a switch means also being interconnected in said controls and disposed for engagement by a part movable with the platform as it reaches its bottom limit and effective to prevent movement of the ram unless the platform is at the bottom limit of its travel.

Another object of the invention is to provide an apparatus of the character stated, wherein the first ram is reciprocated horizontally by air cylinder means, and wherein the second and third rams are reciprocated both horizontally and vertically by air cylinder means, manually initiated and automatically consummated control means being included for carrying out the arranging of the cans in the package complement, and the actuation of the three rams for first bringing the #3 ram against the arranged package complement of cans to oppose the #1 ram in confining and controlling the cans, the movement of the #1 ram and the cans and the #3 ram ahead of them to place the cans at the packaging station, the placement of the #2 ram in position behind the cans, the retraction of the #1 ram and a slight movement of the #3 ram against the cans to take up slack and cooperate with the #2 ram in holding the cans under control during the packaging thereof.

Another object of the invention is to provide an apparatus of the character stated, wherein the control devices include a switch closed by the lowering of the platform to its fully lowered position so that the operating cycle cannot be manually initiated except when the platform is in said fully lowered position.

Another object of the invention is to provide an apparatus of the character stated, wherein the control devices include switch means effective to prevent lowering of the third ram into position opposite the first ram at the can arranging station until after the second ram has moved horizontally its full limit in the direction for transferring a partially sealed package to the final sealing station.

Another object of the invention is to provide in apparatus of the character stated, a can layer and tier sheet supporting and lowering platform having upwardly movable floor sections extending transversely thereof with relation to the direction in which the cans roll onto the platform and longitudinally with relation to the direction in which the first ram pushes the arranged package complement of cans and interposed tier sheets into the slatted receiver at the packaging station, said floor sections lying flat on the platform during the arranging of can layers thereon so that they will not interfere with the arranging of cans, and means being provided for moving the floor sections upwardly as the platform reaches its lower, can-discharging level so as to lift the tier sheets to a position at which they are centered vertically with relation to the cross section of the package complement of cans and at a level at which they will pass freely over the slatted floor of the receiver at the packaging station when the ram pushes the package complement of cans into said receiver.

Another object of the invention is to provide an electric motor for driving the can-driving belts, electrical control means being included for starting the belt-driving function each time the platform reaches its upper limit and for stopping the motor each time the platform reaches its lower limit.

Another object of the invention is to provide in apparatus of the character described, novel rack and pinion actuator means for swinging the tier sheet supporting and releasing vanes to alternately release and hold sheets, air cylinder and piston means for shifting the rack, and electrical control means actuated each time the platform reaches its top position, and including a two-step relay effective on a given platform ascent to direct air into one end of the cylinder, and on the next ascent of the platform to direct air into the other end of said cylinder.

Another object of the invention is to provide in apparatus of the character stated, parallel spaced guides for receiving tier sheets and positioning them between and endwise of the rows of cans as they are being arranged on the platform, means for feeding a web of tier sheet stock into each said guide, and means for severing each web to form a tier sheet and place the same in the respective guide.

With the above and other objects in view that will hereinafter appear, the nature of the invention will be more fully understood by reference to the following detailed description, the appended claims, and the several views illustrated in the accompanying drawings.

In the drawings:

Figures 1, 1a and 1b together comprise a front elevation of the machine when Figures 1 and 1a are joined at A—A' and B—B' and Figures 1a and 1b are joined at the line C—C.

Figure 2 is a left end elevation looking in the direction of the arrow 2 on Figure 1.

Figure 3 is a vertical cross section taken on the line 3—3 on Figure 1a.

Figure 4 is a fragmentary horizontal cross section looking down on the loading platform and the tier sheet receiving guides at the loading station, the #1 ram being shown in position at the left-hand end extremity of the platform, and the section being taken on the line 4—4 on Figure 5.

Figure 5 is a fragmentary vertical cross section taken on the line 5—5 on Figure 4, the first laid or long layer of can rows being shown in the process of being laid on the platform.

Figure 6 is a view similar to Figure 5, the long layer of can rows being shown as completely laid on the platform and cut off from the can row supply by the lowering of the gates.

Figure 7 is a view similar to Figures 5 and 6 and illustrates the platform as having been lowered one step and the second or short row layer of cans in the process of running onto the platform over the layer of cans previously laid thereon.

Figure 8 is a fragmentary vertical cross section showing two sets of the tier sheet receiving guides and illustrating the manner in which a row of cans is received between said guides.

Figure 9 is a fragmentary plan view illustrating the means for oscillating the tier sheet supporting and releasing vanes.

Figure 10 is a fragmentary vertical longitudinal section taken on the line 10—10 on Figure 9.

Figure 11 is a fragmentary vertical cross section taken on the line 11—11 on Figure 10.

Figure 12 is a fragmentary side elevation illustrating the oscillatable platform supporting and lowering shaft, parts being broken away and in section, the platform being shown at its fully lowered position.

Figure 13 is a fragmentary side elevation illustrating the displaceable platform pawl or stop member in engagement with one of the supporting stops on the oscillatable platform supporting and lowering shaft.

Figure 14 is a fragmentary horizontal section taken on the line 14—14 on Figure 12.

Figure 15 is a fragmentary vertical cross section taken on the line 15—15 on Figure 14.

Figure 16 is a fragmentary horizontal section taken on the line 16—16 on Figure 12.

Figure 17 is a perspective view illustrating the platform base frame and guide structure.

Figure 18 is a detailed view illustrating one of the switches effective to control lowering of the platform and operable by the crank through which movement is imparted to the can row cut-off gate structures.

Figures 19 and 19a, when joined at the line D—D, comprise a plan view illustrating the #2 and #3 rams and the supporting and operating devices associated therewith.

Figure 20 is a vertical cross section taken on the line 20—20 on the composite Figures 19—19a.

Figure 21 is a fragmentary front elevation illustrating the manually settable automatically releasable valve.

Figure 22 is a rear elevation illustrating the reverse side of the structure illustrated in Figure 21.

Figure 23 is a vertical cross section taken on the line 23—23 on Figure 21.

Figure 24 is a fragmentary vertical longitudinal section taken through the shiftable can package receiver, the receiver being illustrated in its elevated, can package receiving position.

Figure 25 is an end elevation looking toward the left at the right end of the structure illustrated in Figure 24.

Figure 26 is a somewhat diagrammatic view illustrating a means for feeding and cutting tier sheets from continuous webs of stock.

Figure 27 is a diagrammatic view illustrating a package complement of cans on the lowered platform in position for being pushed by the #1 ram to the wrapping station, the #2 ram being shown in its elevated position and the #3 ram being at its lowered position prior to being moved against the cans of the package complement in opposition to the #1 ram, the package receiver being illustrated in its lowered position and a completed package being in the process of being conveyed away.

Figure 28 is a view similar to Figure 27, the #3 ram being shown as moved against the package complement of cans.

Figure 29 is a view similar to Figure 28, the #1 ram being shown in the process of pushing the package complement of cans and the #3 ram to the wrapping station.

Figure 30 is a view similar to Figure 29, the #2 ram being illustrated as lowered into position behind the package complement of cans and interfitting with the #1 ram.

Figure 31 is a view similar to Figure 30, with the #1 ram retracted and the #3 ram moved slightly to the left to press the package complement of cans against the #2 ram, in which position the formation of the wrapper in tubular form about the package complement of cans and the sealing of one end of the package takes place, the can package receiver remaining in its lowered position.

Figure 32 is a view similar to Figure 31, with the can package receiver shifted to its elevated, can package receiving position, and the platform and #1 ram being shown elevated preparatory to having a package complement of cans arranged thereon during the wrapping and sealing of the previously arranged package complement of cans.

Figure 33 is a view similar to Figure 32, the #3 ram being elevated so that the #2 ram can push the wrapped and partially sealed package into the receiver.

Figure 34 is a view similar to Figure 33, showing the #3 ram moved over to the left into position for subsequently being lowered to the Figure 27 position, and the #2 ram having been moved to the right to shift the can package into the receiver.

Figure 35 is a view similar to Figure 34, the platform and #1 ram being in the process of being lowered and having a package complement of cans arranged

thereon, the #3 ram having been lowered to its position, the #2 ram remaining in its lowered position and the can package receiver being tilted slightly so as to clear said #2 ram and permit lifting thereof.

5 Figure 36 is a view similar to Figure 35, the platform and #1 ram being shown in the fully lowered position, the #2 ram being shown elevated, and the can package receiver being shown in its fully lowered position in which the sealing of the package is completed.

Figure 37 is a somewhat diagrammatic central longitudinal section illustrating a sample form of four-way valve effective to direct pressure fluid into and exhaust the same from the various actuator cylinders for projecting and retracting the plungers for their intended purposes.

Figure 38 is a somewhat diagrammatic sectional view illustrating an arrangement of two sample three-way valves for controlling the horizontal movement of the #3 ram, provision being made for at times opening both ends of the horizontal actuator cylinder to atmosphere.

20 Figure 39 is a diagrammatic view showing an operative connection between the package receiver lifting cylinder and the control valve therefor.

Figure 40 is a fragmentary front elevation illustrating the latch means effective to intercept the #3 ram in its intermediate stop position.

Figure 41 is a horizontal section taken on the line 41—41 on Figure 40.

Figure 42 is a fragmentary view illustrating the switch actuated by movement of the platform to its upper limit and forming a part of the control devices for the tier sheet depositing means.

Figure 43 is a fragmentary view illustrating the ratchet sequence relay and the switch controlled thereby and also forming a part of the control devices for the tier sheet depositing means.

Figure 44 is a fragmentary view illustrating the control switch actuated by the movement of the #1 ram to its fully projected position.

40 Figure 45 is a fragmentary view illustrating the control switch actuated each time the #1 ram is moved to its fully retracted position.

Figure 46 is a fragmentary vertical cross section illustrating the manner in which the wrapper paper contacts the peripheries of the cans at the corners of the package and intermediately of said corners.

Figure 47 is a fragmentary horizontal section illustrating the relation of the #1 and #2 rams when the former is engaged with the cans and the latter is lowered just prior to retraction of the former.

50 Figure 48 is a diagrammatic vertical longitudinal section showing a package complement of cans with tier sheets therebetween and a tubular wrapper application thereabout, the folding in of marginal edge portions at one end of the package being shown in dotted lines.

55 Figure 49 is a line wiring diagram illustrating the electrical connections for the various valves and associated devices including the control switches.

In the machine herein disclosed as an example of embodiment of the invention there are included three stations. The first is the can assembling and arranging station, best shown in Figures 1, 2, 4, and 5 to 7, and generally designated X. The second is the packaging station at which the paper wrapper is applied in tubular form about the package complement of cans shifted to this

second station from the first station. This second station is generally designated Y and is best shown in Figures 1a and 3. While it is preferred that the packaging of the cans be accomplished by the forming of a tubular wrapper thereabout and the sealing of one end of said wrapper at the packaging station Y, it is to be understood that the package complement of cans, assembled and arranged at station X, could be shifted directly into a pre-formed bag at station Y, should it be so desired. The third station has been designated the sealing station Z, and at this point the package is completed by the sealing

of the end thereof left open at the packaging station Y. The sealing station is shown in part at the right in Figure 1a and in Figure 1b, and is illustrated in greater detail in Figures 24 and 25.

The machine frame structure includes a fabricated base portion 5, and at the position of the can arranging station X three corner channels 6 and a corner angle 7 rise from said base portion to support the various mechanisms at this station in conjunction with connected frame portions to be referred to hereinafter.

In this disclosure the package complement of cans is shown as comprising two hundred and sixty-five cans, made up of seven layers with five rows in each layer, four of the layers being long layers having eight cans in each row, and three of the layers being short layers having seven cans in each row. The first laid or lowest layer in each package complement of cans is a long layer, and the last laid or uppermost layer is a long layer, as will be apparent by reference to Figure 3, and in this manner, and because of the manner in which the wrapper is applied, as will appear hereinafter, a compact and tight package having relatively square corners is assured. It is to be understood that this is but an example disclosure, and while the illustrated number and arrangement of cans is preferred, for the particular size of can, the number of cans making up the package complement can be varied to suit varying demands. For example, the arrangement of the long and short rows can be varied at will within the concept of the invention. In other words, a package complement of cans could be made up of layers all of the same length, alternated long and short layers with long layers at both top and bottom, or short layers at both top and bottom, or with a long layer at the bottom and a short layer at the top or vice versa.

For an arrangement of the character stated, five parallel sets of chute tracks or runways 8 are provided and supported at their ends as at 9 on two of the frame channels 6. The tracks 8 are inclined to provide gravity chutes or runways over which the cans 10 roll on their sides toward and into position over the platform on which they are assembled and arranged. The first layer of cans runs directly onto the platform which is raised to a level to thus receive them, as shown in Figures 5 and 6 of the drawings, and in the laying of successive layers the platform is lowered step-by-step, in a manner to be described in detail hereinafter, and each successive layer rolls directly over the layer of cans last laid. Suitable end stop means serve to stop the inrunning of cans and provide for the laying of alternately long and short layers and the staggering and nesting of the layers in the arrangement illustrated in Figure 3, and vertically reciprocable gates cooperate with said end stop means and serve to prevent the inrunning of cans after individual layers are arranged and while the platform is being lowered successive step distances. Overlying guides 11 prevent upward displacement of the cans as they are rolling toward the platform, and the inrolling of cans is further controlled and facilitated by traveling belts 12 frictionally contacting the peripheries of the cans from above. The belts pass over supporting pulleys 13 and 14 one set of which is belt and pulley driven at 15 by the driving motor 16, and pivotally supported and weighted pulleys 17 may be employed, if desired, to accentuate the frictional contact of the driving flights of the belts with the cans.

A bearing pedestal 18 is supported as at 19 on the base portion 5 of the frame structure and includes an upstanding step bearing 20 in which is mounted the lower end of the platform supporting column 21. The upper end of the column is supported in a bearing 22 secured to and depending from a bracket 23 which is secured at 24 to the adjacent frame channel 6. A long sleeve bearing 25 is vertically slidable on the column 21 and has a platform base support 26 projecting integrally therefrom in the manner best shown in Figures 1, 2, 4 and 17. A sec-

ond base support 27 is secured at 28 on the support 26 and projects at approximately a right angular relation and horizontally therefrom and cooperates with a similar base support 29 secured in like manner at 30 to said support 26 in providing the base support structure for the platform as shown in Figure 17. Base bars 31 are secured to the members 26, 27 and 29 in the manner shown in Figure 17 and the platform proper which takes the form of a plate 32 is directly mounted on said bars. The sleeve bearing 25 and column 21 provide the main support for the platform and all loads and bending stresses are imposed upon these supporting devices. However, a guide shaft 33 is uprightly supported in bearings 34 mounted on the frame angle 7 and is surrounded by a slide collar 35 engaged by a fork 36 secured to the platform base member 27, this equipment being effective to secure the platform against any tendency to swing about the axis of the column 21.

An inwardly directed angle member 37 is secured uprightly on the platform base member 27, and an outwardly directed angle member 38 is similarly secured to the platform base member 26, and these angle members project upwardly from the platform in parallel spaced relation opposite the open side of the platform directed toward the can runways 8 from which the can rows are delivered onto the platform. It will be apparent by reference to Figures 2, 4, and 5 to 7 that end stop rails 39 are secured to the angle uprights 37 and 38 in parallel, horizontally disposed pairs, each cooperating pair having opposed angle cut corners 40 engageable by the endmost or lead cans in the rows making up the vertically alternated long layers of cans. Only one such angle cut bar corner is engaged by the cans at the advance end of the lowermost layer which is rolled directly onto the platform plate 32, whereas each other long layer is rolled over a previously laid short layer, just as each short layer is rolled over a previously laid long layer.

In order to provide proper end stops for the can rows making up the short layers, a stop finger 41 is provided for engagement by the endmost can in each row of each of the short layers. These fingers have angle cut can engaging end portions 42 and are slidably mounted in brackets 43 secured to the stop rails 39. Compression springs 44 surrounding plungers 45 slide guided in the brackets and interposed between said brackets and pins 46 projecting laterally from the stop bars 41 constantly tend to retract said bars from their effective positions shown in Figures 5 to 7 to the retracted, out-of-the way or ineffective position illustrated in Figure 2. The positioning of the stop fingers 41 is controlled by upright cam tracks in the form of angle members having vertical portions 47 for holding said fingers projected while cans are being loaded layer-on-layer on the platform, and receding or angle bent relief portions 48 which release the ends of the stop fingers 41 and allow the springs 44 to retract them. The end stop fingers 41 stagger the can rows of each short layer so that they will nest with relation to the can rows in the underlying layer, and then after a long layer of cans is superposed upon such a short layer the end stop rails 39 will serve to stagger the can rows thereof with relation to the can rows of said underlying short layer so that they will nest with relation to the can rows in said underlying short layer and hold them against movement. Hence the positioning contact of the end stop fingers 41 will no longer be needed, and as the platform is lowered through successive steps, as each set of stop fingers 41 come opposite the receding cam portions 48, they will be retracted by their springs 44 and will be out of the way of any possible interference of the transferring of the fully assembled and arranged package complement of cans from the assembling and arranging station X to the packaging station Y. It is to be noted that the can stopping finger surfaces 42 are spaced from the can stopping rail surfaces 40 the distance of a can radius in the direction in which the incoming

cans roll, thereby to assure the proper staggering and nesting of the successively laid can layers.

Intermediately of their upper and lower extremities the stop finger position controlling cam tracks 47, 48 are adjustably mounted at 49 on a channel member 50 secured at its ends on one frame upright 6 and the corner angle 7, as shown in Figures 1 and 4. At their upper ends said tracks are removably clamped at 51 to an angle member 52 secured at its ends to said upright 6 and corner angle 7.

The platform sleeve bearing 25 has a pawl or stop member 53 pivotally supported thereon at 54, as in Fig. 12, and a compression spring 55 interposed between the lower end of said stop member and the sleeve 25 constantly tends to swing the downwardly directed pawl stop shoulder 56 outwardly to its effective position determined by the stop screw 57. The pawl stop shoulder 56 is disposed to engage stops to limit downward step movements of the platform under action of gravity during the assembling of the cans layer after layer on said platform. The pawl or stop member 53 also has an outwardly and downwardly projecting cam surface 58 which is engageable with and displaceable by the stops as the platform is elevated to its initial, first layer receiving position after a package complement of cans has been assembled and arranged thereon and has been discharged therefrom, or in other words, transferred to the packaging station.

The stop shaft 59 is oscillatably mounted in parallel spaced relation to the column 21 in a lower step bearing 60 forming a part of the pedestal 18, and in an upper bearing 61 secured at 62 on the adjacent corner channel 6. This stop shaft is supported at its lower end on a compression spring 63 which is strong enough to hold the shaft up against the limit screw 64 in the upper bearing 61 whenever the weight of the platform is released by retraction of the last effective stop from beneath the platform sleeve carried pawl member 53 by a movement of the stop shaft about its axis, but which will permit the shaft 59 to move down against the bearing seat 65 whenever the weight of the platform is imposed thereon. A control switch 66 is mounted on the bearing 60 in position for having its plunger 67 engaged and depressed to close the switch by a collar 68 secured on the shaft 59 each time the shaft is lowered against the action of the spring 63 by imposition of the weight of the platform on said shaft. Each time a stop is moved away from beneath the platform pawl member 53 to allow the platform to fall a step, the spring 63 will lift the shaft 59 and collar 68 and allow the switch 66 to open for a control purpose to be described hereinafter.

The collar 68 has a radial projection 69 which is oscillatable with the shaft 59 between the spaced stops 70 fixed to the pedestal 18 and with which said projection is engageable to limit the oscillatory movement of the shaft. The oscillatory movement is imparted to the shaft 59 by the projectable and retractable plunger 71 of the cylinder and piston means 72 supported at 73 on the adjacent corner channel 6, said plunger being link connected at 74 with a radial projection from the collar 75 which is secured on the shaft. See Figures 2, 12 and 16.

The arrangement of the stops on the stop shaft 59 is best shown in Figures 2, 12, 13 and 14 from which it will be seen that the stops are in the nature of collars 76 secured in vertically spaced relation on the shaft and each having a radial stop projection 77 and a concentric clearance 78 to one side of said projection. The arrangement of the radial projections and clearances on the successively engageable stop collars is alternated so that the stop projections will be presented in two upright, circumferentially spaced columns. Thus, upon oscillation of the shaft back and forth between the limiting stops 70, a platform supporting stop 77 at one level and in one said column will be moved from beneath the platform pawl member 53 to release the latter and the platform to allow the platform to fall to the next lower

level where the pawl member 53 will be intercepted and stopped by the stop projection 77 next below and in the other column. During the assembly and arrangement of the illustrated seven layers of cans going into the make-up of each package complement of cans, the platform, first supported by the uppermost of the seven stops 77 shown in Figure 2, will fall step-by-step onto the successively presented remaining six stops which are equidistantly spaced, and then after the last layer is laid, and upon removal of the last or seventh stop, the platform will fall a longer step to the level shown in Figures 2 and 12 at which the assembled and arranged package complement of cans is removed from the platform. This last long drop step is determined by engagement of the platform sleeve 25 against the stop collar 79 secured on the column 21.

Elevation of the platform is effected by fluid pressure actuated cylinder and piston means under controls to be described in greater detail hereinafter. The cylinder 80 is connected at 81 to the platform sleeve 25, and its piston 82 is connected at 83 to the before mentioned bracket 23. It will be apparent that when pressure fluid is directed into the upper end of the cylinder, above the piston therein, it will act against the cylinder head and effect a lifting of the platform relative to the fixed piston. The step-by-step lowering of the platform is checked or cushioned by a fluid pressure cylinder and piston means the cylinder 84 of which is secured to the platform sleeve 25, and the piston 85 of which is connected to the before-mentioned bracket 23. Conventional means, not shown, are employed for controlling the escaping of pressure fluid during the checking of the step-by-step falling of the platform.

The platform sleeve 25 also carries a lower limit switch actuator 86 and an upper limit switch actuator 87, the former serving to actuate the switch 88 at the lower travel limit of the platform, and the latter serving to actuate the switch 89 at the upper travel limit of the platform, for control purposes to be described herein-after.

In a vertical grooveway 90 provided on the platform sleeve 25 are removably secured a plurality of switch actuator cams 91 spaced to correspond to the levels at which the alternated, long layers of cans are laid. See Figures 14 and 15. These cams are disposed for engagement with the actuator lever 92 of a double acting selector switch 93 suitably supported on the adjacent frame channel 6. It is to be understood that each time the platform is placed at a level at which a long layer of cans is to be received the correspondingly positioned cam 91 will engage the lever 92 and actuate the switch plunger 94 to connect the switch in a long layer control circuit, and each time the platform is placed at the intermediate levels at which short layers of cans are to be received, the switch actuator lever 92 will be free to swing out into the spaces between the cams 91 and allow the switch plunger to move to its other position effective to connect the switch in a short layer control circuit. These control circuits will be described in greater detail hereinafter.

As before mentioned, vertically reciprocable gates control the inrunning of cans and cooperate with the previously described long and short layer and row end stops 40 and 42 in providing for the staggering and nesting of the cans in the rows of the long and short layers in the manner clearly illustrated in Figures 3 and 7. Two sets of gates are provided, one set 95 being disposed to cut off the inrunning of cans in the manner illustrated in Figure 6 when a long layer is being laid, and the other set 96 being disposed to cut off the inrunning of cans when a short layer is being laid, as in Figure 7. The gates are vertically reciprocable in guides 97 attached at 98 to the plates forming a part of the tier sheet holding and feeding guides generally designated 100 and to be described in detail hereinafter and which are in turn supported by strips projecting from clamps 99 secured on

upper and lower mounting shafts 101 and 102 mounted as at 103 on the two adjacent corner channels 6. The gate sets are spaced apart the distance of a can radius in the direction toward the end stop rails 39 and fingers 42. As illustrated in Figure 6 the spacing between a given long layer end stop 40 and the long layer cut-off gates 95 is such that when the foremost cans in the layer rows come against the end stop 40 and the cut-off gates 95 are lowered, said stop and gates confine between them a long layer of five rows each containing eight cans, and the inrunning of additional cans will be stopped. In like manner, the spacing between a given short layer controlling finger set 42 and the short layer cut-off gates 96 is such that when the foremost cans in the layer rows come against the fingers 42 as shown in dotted lines in Figure 7 and the cut-off gates 96 are then lowered, said stops and gates will confine between them a short layer of five rows each containing seven cans, and the inrunning of additional cans will be stopped.

It should be understood that the long and short layer gates 95 and 96 are so dimensioned and positioned that they will not move down far enough to wedge between cans when they are lowered. For example, see Figure 6. By thus avoiding wedging side contact with the cans, all danger of sidewise displacement of cans and upward buckling of can rows is eliminated.

In order to provide for the vertical reciprocation of the cut-off gates 95 and 96, upper and lower actuator shafts 104 and 105 are provided, and these are rockably mounted in bearings 106 attached to the frame standards 6. A crank arm 107 is secured to the upper or short row actuator shaft, and a crank arm 108 is secured to the lower or long row actuator shaft. The arm 107 is connected with the piston rod 109 of a pressure fluid actuator cylinder means 110, and the arm 108 is connected with the piston rod 111 of a pressure fluid actuator cylinder 112, said cylinders being supported at 113 on the frame extension 114. The short layer gates 96 are connected at 115 with the crank arms 116 secured on the upper actuator shaft 104, and the long layer gates 95 are connected at 117 with the crank arms 118 secured to the lower actuator shaft 105.

Control devices to be described in greater detail herein-after are provided for assuring that all rows in each layer of cans arranged on the platform are full, and that the platform cannot be lowered until such rows are full and the stop gates have been lowered to prevent further inrunning of cans. As a part of these control devices there are provided a set of five long row switches 119 operable by levers 120 carrying rollers 121 at their ends disposed in position for being lifted or moved to the switch closing position only when a can comes against an end stop means 40, and in normal operation of the machine each can thus coming against an end stop means 40 is closely followed by cans making up a full row complement thus assuring that the particular row is full when a given switch 119 is actuated, and by connecting all said switches 119 in series it can also be assured that the control circuit will not be completed until all such switches have been closed, thus assuring also that the whole layer is full. In like manner there are provided five series connected switches 122 operable by shorter levers 123 carrying rollers 124 at their ends and each disposed in position for being lifted only when a can comes against an end stop finger 42, thus assuring full complements of cans in each short layer also in the same manner described in connection with the making up of the long layers. See Figures 4 to 7. All of the switches of both sets are of the normally closed type so that they will be held in the open or circuit breaking position by the levers when they are freely suspended and not raised by can contact, the can lifting of said levers serving to free the switch buttons and allow them to move to the circuit completing positions. Stops 125 limit the downward swinging movement of the switch actuator levers,

Included in the controls just above referred to and to be described in greater detail hereinafter are two switches 126 and 127. Supported on the before-mentioned bracket 23 in position for having their respective actuator levers engaged by cams 128 and 129 movable with the shafts 104 and 105 to complete the respective control circuit as the respective crank 107 or 108 is completing its function of lowering the gates 95 or 96 to the long or short layer cut off position. See Figures 2 and 18.

As the can rows roll into position on the platform, or upon a previously laid layer of cans on the platform, they roll from the tracks or runways 8 into spaces or guideways formed between the upstanding, parallel spaced tier sheet holding and feeding guides generally designated 100 and which are best shown in Figures 1, 2 and 4 through 8. These guides are six in number and disposed to place a tier sheet 130 between each adjacent pair of can rows and one endwise of each endmost can row. The tier sheets are deposited on the platform and move down step-by-step with the same so that when the platform is fully lowered and the package complement of cans is fully assembled and arranged thereon it will have have a tier sheet at each end thereof and one between each two adjacent tiers of cans, each such tier being made up of seven superposed rows of cans, four long rows of eight cans each and three short rows of seven cans each.

A hand fed tier sheet positioning means will first be described, but in a modified form means are provided for feeding and cutting the tier sheets from continuous webs of stock. In this hand fed form each guide generally designated 100 comprises two parallel plates 131 and 132 forming between them a tier sheet guideway 133, and two additional parallel plates 134 and 135 forming between them a tier sheet guideway 136. Thus each guide provides two side-by-side guideways into which the tier sheets can be fed by hand through upwardly flared receiving mouths 137. The practice is to hold a tier sheet in one guideway of a guide while a tier sheet is moving down with the platform in the companion guideway, and then to automatically release the held tier sheet when the platform is elevated to start another cycle so that it can then move down with the platform in the next loading cycle while another tier sheet is placed and held in the previously open guideway. The means for alternately closing and opening the companion guideways 133 and 136 of a guide generally designated 100 is best shown in Figures 2 and 8 through 11.

Upon frame extension means 138 is mounted a support 139 having a slot 140 therein in which are adjustably mounted a plurality of bearings 141, one for each tier sheet guide 100. Each bearing 141 rockably supports one end of a shaft 142, the other end of which is supported in a bearing 143 mounted centrally at the other end of the respective guide 100. Each shaft 142 carries a vane 144 and is oscillatable through 180° to alternately open and close the lower or discharge outlet of the companion guideways 133 and 136 in the manner illustrated in Figure 8. Each shaft 142 also has a pinion 145 thereon, and all of the pinions are engaged by a rack 146 which is slidable in a groove provided therefor in the support 139. The rack has a depending actuator 147 connected with the piston rod 148 of a piston and cylinder means 149 also mounted on the support 139. The cylinder means is automatically controlled in a manner to be described hereinafter to move the piston in one direction or the other each time the platform is elevated to start a new loading cycle. The desired 180° of movement of the vane 144 is limited by the spaced abutments 150 which are engageable with the stop 151 as the rack 146 is moved in one direction or the other by the cylinder means 149.

In the modified form of tier sheet feeding means, six webs 152 of tier sheet stock are fed from individual supply rolls 153. It is preferred that the webs fed from

the rolls 153 farthest to the left and to the right as shown in Figure 26 shall be of chipboard, and that the webs fed from the four rolls disposed intermediately of these endmost webs be thinner kraft paper. Thus in the can package ultimately formed, the chipboard tier sheets will be disposed at the ends of the package and the kraft paper tier sheets will be disposed between the adjacent tiers of cans. The webs 152 first pass over idler guide rolls 154 and about engaging curl removing and brake rolls 155, and thence over full length fixedly mounted metal idler rolls 156 disposed to direct the individual webs downwardly into guides 157 vertically aligned with the guides 158 through which the individual tier sheets ultimately are to be placed during the lowering of the platform and the assembling and arranging of can layers thereon.

A carrier 159 is provided and is horizontally slideable on guide means 160, being movable in one direction by spring means 161 and in the other direction by air cylinder means 162 controlled by a solenoid valve diagrammatically indicated at 163 and being of well known conventional form in which the valve is solenoid shifted when the solenoid is energized to direct air into the cylinder to move the carrier to the left, against the action of the spring 161, and shiftable by spring means when the solenoid is deenergized to exhaust air from the cylinder and allow the spring 161 to return the carrier to the right. Short length rubber pinch rolls 164 are mounted on and shiftable with the carrier 159, and these are continuously driven by any suitable means, as by the driver shaft 165 gear coupled with the pinch rolls as at 166 and in turn driven by flexible shaft means 167. It will be apparent that each time the carrier 159 is moved to the left it will cause the rolls 164 to grip and feed the webs 152, and each time the carrier is retracted to the right the grip rolls 164 will be moved away and the movement of the webs will stop at once because of the brake rolls 155.

Reciprocable knife means 168 traverses the guides 157, and the movable knife is shiftable by a double acting air cylinder 169 controlled by an air valve diagrammatically indicated at 170 as being shiftable in one direction, for effecting a projection of the knife to sever tier sheet lengths in the guides 157 and 158, by a solenoid 171, and in the other direction, for effecting a retraction of said knife, by a solenoid 172. A limit switch 173 is connected with the solenoid 171 and with the power lines 174 and 175 by the conductors 176 and 177 and is engageable by the movable knife after it has severed the tier sheet lengths from the webs 152 to effect an energizing of the solenoid 171 and a retraction of the web severing knife. The companion solenoid 172 is connected with said power lines and with a control switch 178 through conductor lines 179 and 180, and said switch is operable by a single direction actuator 181 movable with the platform so that an energizing of the solenoid 172 and a projection of the knife to sever tier sheet lengths from the webs 152 will be effected each time the platform moves up into position to receive and support the tier sheets.

In order to effect a shifting of the carrier 159 to the right to discontinue the feeding of the webs 152 after proper tier sheet lengths have been fed into the guides, and before the knife means is actuated, so that the webs will be stationary when the cutting of the tier sheet lengths is effected, a fed web actuated control switch 182 is provided. This switch is vertically-adjustably mounted as at 183 so that the point at which it stops the web feeding, and therefore the length of the tier sheets, can be varied, and the switch is of the type wherein the contact making member constantly tends to move to the open, circuit breaking position, and it is normally held closed by a light spring 184 disposed to hold a pivoted lever 185 against the switch plunger. See Figure 26. The free end of the lever 185 projects into the path of one of the fed webs and when lightly contacted and displaced by said web will permit the switch to assume its circuit breaking condi-

tion to break the control circuit through the conductors 186 and 187 and the solenoid valve 163 and bring about a shifting away of the grip rolls 164 and a discontinuance of the web feed. This control circuit will remain broken 5 so long as the paper continues to contact and displace the lever 185, and the now stationary web ends remain suspended through the web severing means. When the platform, in being elevated to start a new loading cycle, reaches its upper limit, it brings about an actuation of 10 the web severing means by actuating the switch 178 and energizing the solenoid 172, and the severed tier sheets fall upon the platform to be lowered therewith as it moves down step-by-step. The switch control lever 185 will remain in its displaced position shown in dotted lines 15 in Figure 26 until the controlling tier sheet moves down far enough to release the same, at which time the circuit will again be completed through the switch 182 to energize the solenoid 163 and shift the grip rolls 164 to the web feeding position.

20 It will be apparent by reference to Figures 4 through 8 of the drawings that a horizontal support bar 188 is mounted, cantilever fashion as at 189, on each of the long row gates 95, and a bar 190 is supported in like manner at 191 on each of the short row gates 96, said bars extending over the platform space in the manner clearly illustrated in Figures 4 and 5. An inverted U-shaped presser 192 is vertically-slidably mounted over each of the bars 188 and 190 with its lower edges depending in position for being engageable downwardly with cans on the 25 platform when the respective gates 95 or 96 are lowered upon completion of the running in of the can rows. One or more plungers 193 extend upwardly from each bar through clearing apertures in the respective presser and each plunger has an abutment member 194 at its upper ends. Compression springs 195 surround the plungers between the pressers and the abutments and are effective to constantly urge the pressers downwardly. The guides 30 97 are provided with clearances 196 to clear the pressers 192, and the gates 96 are provided with clearances 197 to clear the pressers not carried thereby, as will be apparent by reference to Figures 5 and 8. It will be noted that two of the pressers are provided in the space between each two tier sheet guides 100, or in other words, in position for overlying each row of cans, one carried by a short row gate and one carried by a long row gate. Thus 35 one presser 192 will be effective to engage and apply pressure to each row of cans as the platform is being lowered regardless of whether the row is fixed in position between a long row gate and a long row end stop, or between a short row gate and a short row end stop. As a given set of gates is lowered the pressers carried thereby will engage the underlying rows of cans forming the last laid layer on the platform and will yield upwardly, storing energy in the springs 195 as the gates move to their lowermost positions. Thus, after each inrunning of can rows 40 has been stopped, and before and while the platform is starting to descend a step to receive the next layer of cans, or to move down the final long step which places the assembled and arranged package complement of cans for being discharged from the platform, the pressers will apply pressure to the cans and will follow down and apply pressure to the downwardly moving cans as they start their downward movement, thereby to overcome inertia effects, frictional contact or other forces and assure against 45 any displacement of the arranged cans from the layer planes in which they are arranged.

40 At the open side of the platform opposite the end stops 42 and 42 and extending downwardly from the level at which the cans roll into position over the platform the frame carries a wall plate 198 which cooperates with 45 said end stops in holding the assembled and arranged cans in place as the platform is being lowered. It is also to be noted by reference to Figures 1 and 2 that guide members 199 are secured to and depend from the end 50 most tier sheet guide unit toward the left in Figure 1.

and serve the purpose of supporting the tier sheet exposed at that end of the package complement of cans and the cans against falling away from their normal assembled position. Similar tier sheet supporting guide means 200 is swingably suspended adjacent the endmost tier sheet guide unit at the other end of the assembled package complement of cans, or at the right of Figure 1 toward the packaging station Y, but it is to be understood that this last-mentioned guide means is swingably displaceable during the discharging of the cans from the platform to said packaging station so that it will not interfere with such can shifting.

The discharging of the assembled and arranged package complement of cans from the platform at station X and the transferring of said cans to the packaging station Y is accomplished by the horizontally reciprocable so-called #1 ram generally designated 201 and which is carried at the advance end of a piston plunger 202 operable in the cylinder 203. The cylinder is supported at its inner end at 204 on bars 205 attached at their ends to the sleeve bearing 25 and the upright angle member 37 of the frame platform structure. See Figures 1, 2 and 4. At its outer end the cylinder is supported on downwardly and inwardly angled rods 206 secured at their inner ends at 207 on the platform structure. Thus the ram and its operating means are supported on and are vertically movable with the platform. The plunger 202 carries a head 208 to which are attached two vertically spaced horizontal tubes 209, and to these tubes are secured a plurality of uprightly disposed parallel spaced tubes 210 which comprise the head of the ram generally designated 201. It will be apparent by reference to Figure 2 that the spacing of the upright components 210 of the ram head permits said head to move forwardly and backwardly without interfering with the tier sheet guides 199. Rollers 211 supported at 212 on the ram head 201 support the same in its movements of projection and retraction across the platform floor 32.

Longitudinally hinged, upwardly movable floor sections 213 are provided in the platform floor 32 and these extend in the direction of projection and retraction of the ram head and transversely with relation to the direction in which the cans roll onto the platform. During the rolling in of the can rows the floor sections 213 lie flat and flush with the platform floor 32 so that they will in nowise interfere with the assembling and arranging of cans. However, when the platform is lowered to its can discharging position, as illustrated in Figures 1 and 2, the floor sections 213 are engaged by stationary screw abutments 214 and are swung upwardly to project above the platform floor. This serves to elevate the tier sheets 130 to prevent fouling thereof as the ram head 201 pushes them off the platform floor 32 and into the receiving means at the packaging station Y. This lifting of the tier sheets serves to center them vertically with relation to the cross section of the package complement of cans, and this centered relation is retained at the packaging station.

When the package complement of cans is discharged from the platform and transferred to the packaging station Y it is received in a form generally designated 215 and which retains the compact arrangement of the cans during the packaging thereof. The packaging station, and this form, are best shown in Figures 1a and 3.

In Figure 1a a package complement of cans is shown in dot and dash lines as placed in the packaging position within the form 215. However, this is to be understood as constituting a phantom position illustration only, showing the relation of the package complement of cans and the form in which it is received. Obviously the #3 ram, to be referred to in detail hereinafter and shown at the extreme left of the form in Figure 1a, would not be in that position with a package complement of cans in the form 215, as will become apparent hereinafter.

The two corner frame channels 6 adjacent the packaging station Y support a cross shelf or bracket 216 on which a plurality of floor slats 217 are secured in parallel spaced relation, projecting cantilever-fashion toward the sealing station Z and providing the floor of the form. The form as a whole is U-shaped in vertical cross section and has each side wall made up of a plurality of slats 218, which are horizontal disposed in parallel spaced relation and supported cantilever-fashion at their receiving ends on mounting standards 219 secured at 220 on the shelf 216. It is to be noted that the adjacent, inwardly directed edges of the floor and side wall slats 217 and 218 are beveled so as to provide between said slats thin edge defined openings into which the peripheral wall portions of cans in the bottom layer and at the ends of the several long layers project into very close proximity to the planes of the outer faces of the slats 218 and the bottom faces of the slats 217, thereby making it possible for packaging paper extending about the form to lie very close to the cans and assure the provision of a tight package. Because of the free ended mounting of the form slats it would be quite practical to telescope a pre-formed paper bag over the free end of the form and push the package complement of cans into the form and the bag thereover, and then to push the cans and the bag off the form to be finally closed and sealed. However, it is preferred that the packaging of the cans be accomplished by forming a paper wrapper in tubular shape about the form and the package complement of cans therein, to seal the end of the package at the free end of the form while still in said form, and then to push the package thus partially completed to the sealing station Z for final closing and sealing.

In order to facilitate this purpose a U-shaped cradle or guide 221 is supported on an extension of the frame base 5 beneath the form 215. Previously cut and properly glued wrappers may be fed by hand into the receiving end 222 of the guide 221 but it is preferred that this placement of the paper wrappers be effected by the mechanisms disclosed in the copending application for United States Letters Patent Serial Number 355,705 filed on May 18, 1953 by Heinrich Ernst Haase and entitled "Wrapper Cutting, Gluing and Feeding Apparatus," now Patent No. 2,778,176.

When a prepared and properly glued wrapper is placed in the cradle 221 an operator standing at the side thereof toward the left as view in Figure 3 can grasp the leading edge thereof at the discharge end 223 of the cradle or guide and draw it up in front of the thin facing plate 224 secured to the outer faces of the side wall slats 218 at that side and having the outwardly turned longitudinal edges 225 at its upper and lower extremities. The operator can then reach over the form and grasp the trailing edge of the wrapper above the receiving end 222 of the cradle and draw it forward tightly over the cans, forming a lapped seam and sealing the same against the other end of the wrapper against the plate 234. This manipulation of the wrapper edges can be facilitated by use of the clamp bar 226 pivotally supported at 227 on frame standards 228 and operable through the medium of the link 229 and treadle 230 connected with the pivot shaft crank extension 231. The clamp bar is normally held in its retracted position shown in Figure 3 by the retractile spring 232, and by depressing the treadle 230 the clamp bar can be moved toward the form plate 224.

It will be apparent by reference to Figure 4 that the platform floor plate 32 may be notched at 233 to fit over the angle cut ends 234 of the form floor slats 217 so as to minimize chances of obstruction to smooth discharging of the package complement of cans and the intermediate and end closure tier sheets from the platform into the receiving form at the packaging station. It will also be apparent that the bottom slats 217 farthest to the sides of the form bottom are lined up

with the ram head supporting rollers 211 so as to provide tracks on which to receive and align the rollers as the #1 ram head 201 pushes the package complement of cans into the form to the position shown in dotted lines in Figure 1a, and for this reason the rollers 211 are grooved in the manner illustrated.

The thin, outwardly turned edges 225 of the form plate against which the side seam of the tubular paper wrapper is formed are not indispensable but when used serve to minimize surface contact of glued marginal portions of the wrapper tube as the partially completed package of cans is being shifted from the form to the final sealing station Z. For similar reasons the side slats 218 at the opposite side of the form may be provided with thin edged angle pieces 235, if desired.

It has been explained hereinabove that the apparatus disclosed herein can be used in bagging cans or in the packaging of the cans in snugly applied wrappers. While the snugly applied wrappers and the resulting compact and tight packages present marked advantages and are preferred, there might be occasions when less tight packages would find favor. For example, should conditions of humidity in packaging or storing locales suggest looser packaging of the cans, the wrappers could be applied over a simple U-shaped form devoid of the wall and bottom slots which are effective to allow the can peripheries to project into direct contact with the wrapping paper during the formation of the paper tube about the package complements of cans.

It has been pointed out hereinbefore that the apparatus includes three ram structures, one which has been described in detail and is effective to push the package complement of cans from the platform at station X to the packaging station Y, a second which is effective to push the partially completed package from the packaging station Y to the final sealing station Z, and a third which is effective to cooperate with the number one ram in maintaining perfect control of the assembled and arranged cans of each package complement of cans as it is being moved from the platform to the packaging station. The remaining ram structures will now be described, proceeding first with the number two ram because of certain characteristics thereof, despite the fact that in the step sequences in operation of the machine, the number three ram comes into active function in engaging the package complement of cans before the number two ram. The ram structures, their mountings and their operating devices are best shown in Figures 1a, 1b, 3, 19, 19a and 20.

The number two ram is generally designated 236, and the ram head comprises a cross angle head piece 237 from which depend a plurality of uprightly disposed, equidistantly spaced tubes 238, the latter being free at their lower ends as will be clearly apparent by reference to Figure 3. It should be understood that the tubes 238 of the number two ram head are cooperatively spaced with relation to the upright tubes 210 of the number one ram head so that when the number two ram is lowered behind the package at the packaging station Y, said tube sets will be able to lie in approximately the same plane without interference, the tubes of one set interfitting between those of the other set in the manner illustrated in Figure 47.

The head piece 237 of the number two ram is secured at 239 to the horizontal extension 240 of the upright and laterally offset carrier plunger or tube 241 which is vertically reciprocable in the guide 242 attached at 243 to the bracket plate 244 forming a part of the carrier sleeve 245. The sleeve 245 is horizontally slidable on a guiding and supporting tube 246 which is secured at one end to a mounting plate 247 attached to the frame structure cross channel 248, and at its other end, as at 249, to the horizontal supporting channel 250 which is in turn supported at the lower end of a supporting frame channel 251. The guide 242 has a mounting flange ex-

tension 252 whereon is supported a fluid pressure actuator cylinder 253, and the vertically reciprocable actuator plunger 254 of this cylinder and piston equipment extends upwardly out of the cylinder and is attached at its upper end to a connector means 255 also attached to the upper end of the ram plunger 241 and to the upper end of a depending switch actuating plunger 256. The plunger 256 carries an actuator cam 257 at its lower end which serves at times to actuate the fixedly mounted control switch 258 for a purpose to be described hereinafter. The plunger 256 is slidable in a guide sleeve 259 supported on an extension 260 from the upper portion of the guide 242. A horizontally disposed fluid pressure cylinder 261 is secured at 262 to the mounting plate 247, and the reciprocable plunger 263 of this cylinder and piston equipment is attached at 264 to the before mentioned carrier sleeve 245. It will be apparent from the foregoing that by properly introducing and exhausting pressure fluid into and from the cylinder 253, upward or downward movement can be imparted to the second ram head 236, and by properly introducing and exhausting pressure fluid into and from the cylinder 261, horizontal reciprocating movement can be imparted to the upright guide 242 and to said ram head 236.

The carrier sleeve 245 carries a switch actuator cam 265 at the end thereof toward the sealing station Z, also an adjustable stop 266 and a valve latch tripper rod 267. At its other end the sleeve carries a stop 268 engageable with the mounting plate 247, and this stop and the stop 266 which is engageable with the abutment bracket 269 clamped on the support tube 246 serve to limit movement back and forth of the sleeve 245 and the supported number two ram. The bracket 269 supports an extension 270 whereon is mounted a control switch 271 engageable by the cam 265. A control valve 272 depends from the extension 270 and has its flow controlling plunger 273 downwardly directed in position for being engaged by a lug 274 projecting from a hand lever 275 pivotally supported at 276. A latch member 277 is pivotally suspended from the extension 270 and is equipped with a retaining notch 278 which is engageable by the notched end 279 of the hand lever extension 280. When the hand lever is moved to the dotted line position shown in Figure 21 to open the valve 272, the latch member 277 swings down to cause the notch 278 to engage with the lever end 280 and secure the parts in the valve open position shown in dotted lines. When the sleeve 245 moves to the stop position shown in Figure 21 the rod 267 will trip the latch 277 and permit the valve to close. The purposes of these control parts will become apparent as the description progresses.

A stabilizer and support rod 281 is provided paralleling the support tube 246 and has one end thereof secured at 282 to the cross channel 248 and its other end secured at 283 to the cross channel 250. An extension 284 from the sleeve 245 is engaged with a collar 285 slidable on the rod 281 and serves to secure the sleeve from turning about the axis of the tube 246 on which it is slidably supported. This rod also supports a depending standard 286 at the lower end of which is mounted a control switch 287 in position for being engaged by a cam 288 on the horizontal supporting extension 240 of the number two ram head when the latter is moved to the limit of its travel toward the sealing station Z. The purpose of this switch will be described hereinafter.

The number three ram is generally designated 289, and the ram head comprises a rectangular face plate 290 having an unobstructed flat front face presented toward the can assembling and arranging station X. Clamp brackets 291 are provided at the rear face of the face plate and are adjustably clamped on the peripheral edges of a mounting plate 292 which is secured at 293 to the laterally and forwardly offset, horizontal extension 294 from the upright, vertically reciprocable carrier plunger 295. It will be apparent by reference to Figures 3 and

19 that whereas the plunger 241 by which the number two ram is carried is disposed at one side of and above the form 215 at the packaging station Y, the number three ram carrying plunger 295 is disposed at the opposite side of and above said form. The carrier plunger 295 is vertically reciprocable in the guide 296 attached at 297 to the bracket plate 298 forming a part of the carrier sleeve 299. The sleeve 299 is horizontally slideable on the guiding and supporting tube 300 which is secured at one end to a mounting plate 301 attached to the frame structure cross channel 248, and at its other end, as at 302 to the before mentioned horizontal supporting channel 250. The guide 296 has a mounting flange extension 303 whereon is supported a fluid pressure actuator cylinder 304, and the vertically reciprocable actuator plunger 305 of this cylinder and piston equipment extends upwardly out of the cylinder and is attached at 306 to the upper end extension of the ram plunger 295 so as to impart its reciprocatory movement to the number three ram. The plungers 295 and 305 also are attached at 307 to a switch actuator plunger 308 which is equipped with an actuator cam 309 at its lower end and is slideable in a guide sleeve 310 supported on an extension 311 from the upper portion of the guide 296. A horizontally disposed fluid pressure cylinder 312 is secured at 313 to the mounting plate 301, and the plunger 314 of this cylinder and piston equipment is attached at 315 to the before mentioned carrier sleeve 299. It will be apparent from the foregoing that by properly introducing and exhausting pressure fluid into and from the cylinder 304, upward or downward movement can be imparted to the third ram head 289, and by properly introducing and exhausting pressure fluid into and from the cylinder 312, horizontal reciprocatory movement can be imparted to the upright guide 296 and to said ram head 289.

The carrier sleeve 299 carries a switch actuator cam 316 at the end thereof toward the sealing station Z, and also an adjustable stop 317. At its other end the sleeve carries a stop 318 engageable with a stop 319 adjustably supported on the bracket 313 by which the tube 300 is supported on the framing, and the stop 318, together with the stop 317 which is engageable with the abutment bracket 320 secured on the tube 300, serve to limit movement back and forth of the sleeve and the supported number three ram. However, the stop 318 controls the extreme advanced position of the number three ram in which it engages with the package complement of cans before they are pushed by the number one ram from the loading station X to the packaging station Y. This position is shown in Figures 19 and 28. On each movement of the number three ram toward the loading station while it is elevated, it must be stopped short of its extreme advanced position, and then moved to its can contacting position at the loading station only after it has been lowered. Compare Figures 34, 27 and 28. This intermediate stopping of the number three ram is accomplished by a solenoid controlled latch means generally designated 321 and which is best shown in Figures 19, 40 and 41. This latch means includes a stop 322 carried by the sleeve 299 and which is engageable with the free end of a latch member 323 pivotally supported on the framing as at 324. A solenoid 325, supported as at 326 is link connected at 327 with the latch member and is effective when energized to lift the latch from its normal depressed position intended for intercepting the sleeve stop 318 and stopping movement of the number three ram. When the solenoid is energized the latch will be freed to allow the ram to move to the limit permitted by the stop 318. When the solenoid is deenergized the latch falls into position for intercepting the ram.

It is important to note, by reference to Figure 3, that the number three ram plate 290 is dimensioned so as to leave a clear space about the whole perimeter thereof within the dimensions of the engaged end of a package

complement of cans. This makes it possible to fold the longitudinally extending marginal edge portions of the paper wrapper tube inwardly over and against the tier sheet at the engaged end of the cans, thereby to effect a sealing of this end of the package while the number three ram is engaging the cans and holding them in position.

5 The bracket 320 on the tube 300 supports a control switch 328 which is engageable by the cam 316 when the number three ram has been moved the intended maximum distance toward the sealing station Z. At its other end the carrier sleeve 299 carries an adjustable actuator plunger 329 which is engageable with the frame supported switch 330 when the number three ram has been moved 10 the intended maximum distance toward the can loading station X.

15 A bracket 331 is secured on the rod 281 and carries an upright 332 on the upper end of which a control switch 333 is mounted in position for being engaged and 20 actuated by the cam 309 supported by the plunger 308 which is movable horizontally with the number three ram. This engagement of the cam 309 and switch 333 takes place when the ram has been moved to the limit of its horizontal travel toward the sealing station Z and 25 then has been elevated to the upper limit of its vertical travel. The bracket 331 also supports a horizontal member 334 which provides a support for the control switch 335.

An extension 336 from the sleeve 299 is engaged with 30 a collar 337 slideable on the rod 281 and serves to secure the sleeve from turning about the axis of the tube 300 on which it is slidably supported. The extension also carries an actuator cam 338 disposed to engage with and actuate the switch 335.

35 A travel check piston plunger 339 is secured at 340 to the supporting tube 246 and is slideable in the cylinder 341 which is movable with the sleeve 245. It is to be understood that the rate of ingress and egress of fluid into and from the cylinder is controlled in any approved 40 manner to suitably check the rate at which the number three ram will be moved in a horizontal direction to and from its various operative positions.

45 Limiting stop means such as is illustrated at 342 in Figure 1a may be provided for limiting the upward movement of the ram plungers 241 and 295.

The purpose and manner of operation of the various control devices referred to briefly hereinabove will be described in greater detail hereinafter.

50 The means for receiving the partially completed package of cans at the final sealing station Z will now be described. In close proximity to the packaging station Y and endwise of the delivery end of the form 215 thereat there is provided a base frame 343, and a pair of parallel side frames 344 supported on uprights 345 and 55 346 rising from said base frame. Attached to the inner face of each frame 344 is a guide track 347. The tracks are in opposed alignment and each includes a straight horizontal portion 348 and a straight upright portion 349 connected by a well rounded curved portion 350. These tracks serve to shiftably support the can package receiver generally designated 351 so that it can be moved between the elevated, horizontal position shown in Figure 24 in which it receives the partially sealed package, and the lowered upright position shown in Figures 1a and 1b in 60 which the end of the package remaining open is presented upwardly to facilitate the final closing and sealing thereof.

65 The receiver 351, when elevated as shown in Figure 24 is U-shaped in horizontal cross section, the wall 352 comprising the base of the U and the opposing side walls 353 the legs or uprights of the U. It will be noted that the left hand edges of the walls 352 and 353, as viewed in Figure 24 are disposed in close proximity to the delivery end of the form 215 so as to receive the partially 70 completed package therefrom with great facility. The 75

walls 352 and 353 are supported on a frame structure comprising three longitudinal tubes 354 and two transverse tubes 355 secured to the wall 352, and upright side tubes 356 are secured to and extend from the tubes 355 and are secured by brackets 357 to the side walls 353. A roller frame composed of side angles 358, connecting tubes 359 and transverse rollers 360 is secured by brackets 361 over the ends of the walls 353 remote from the form 215, and this frame forms an end closure for the receiver when it is elevated, as shown in Figure 24, and a bottom for the same when it is lowered to the position shown in Figures 1a and 1b. The rollers greatly facilitate the rolling out of the package, after it is completely sealed, onto the railway 362 or other conveyor provided for moving the completed packages away from the machine.

A pair of spaced support members 363 extend into the space between the side frames 344 from each of two of the longitudinal tubes 354 and these are equipped with rollers 364 which are supported and guided in the tracks 347 and serve to control the position of the receiver 351. Two of the members 363 are opposed one to the other approximately centrally of the base wall 352 and these are cross connected by a shaft 365. A rock shaft 366 is mounted in the frame bearings 367 and a crank arm 368 is secured on this shaft and is connected at its outer end, as an oscillating actuator, with the receiver cross shaft 365. A fluid pressure cylinder 369 is pivotally supported on the base structure at its lower end, as at 370, and the reciprocable piston plunger of this cylinder and piston actuator is connected at 371 with the crank arm 368 so that when the piston plunger is projected it will shift the receiver 351 to its elevated position shown in Figure 24. It is preferred that the receiver lifting cylinder 369 be connected at its lower end beneath its piston through a conduit 372 with the pressure discharge port of the valve 272, and that it have a controlled outlet bleed port 373 at its upper end opening to atmosphere and effective to choke the escape of air from the cylinder above its piston in a manner for checking movement of the receiver to its elevated, package receiving position, and to trap air which will serve to expand as the receiver is being moved by package contact at the commencement of the return or lowering movement of the receiver and aid such return movement. This arrangement is diagrammatically illustrated in Figure 39 from which it will be apparent that the spring 374 constantly tends to move the valve plunger 273 to its projected position shown in said figure, in which position the air supply line 375 is sealed off and the cylinder connecting duct 372 is connected with the exhaust port 376. When the valve plunger is shifted by swinging of the lever 275 to the left, and held in that position by the latch 277, pressure fluid from the supply line 375 will be directed through the duct 372 into the lower end of the cylinder 369 to effect a lifting of the package receiver 351. Stop members 377 extending perpendicularly with relation to the receiver wall 352 are movable between and engageable with the fixed stops 378 for accurately determining the upper and lower limits of movement of the receiver.

Should a supplementary checking means be desired to check the movements of the receiver as it approaches its upper and lower limits in view of variations in package makeup or for other reasons, there may be provided a hydro-check cylinder 379 which is swingably mounted at 380 on one of the frame uprights 346 and has its piston plunger slidably extended through a pivoted block 381 carried at the free end of a crank arm 382 secured on the rock shaft 366. Spaced abutments 383 on the plunger and engaged by the block 381 as the receiver is approaching a lifting or lowering movement limit impart movement to the plunger and this movement is resisted or cushioned in the cylinder by the controlled passage of fluid into and from the respective ends of the cylinder

in the well-known manner and under control of the adjusting means 384.

A control switch 385 is supported at 386 on one of the frame uprights 345, and a pivoted interponent 387 overlies the actuator plunger of this switch. A switch actuator is mounted on and movable with the crank arm 382 and the element 388 thereof which engages and actuates the switch through the interponent is to be understood as having a knee-joint mounting effective to cause a displacement of the interponent and an actuation of the switch 385 only momentarily each time the receiver starts upward away from its lowered position but which is freely swingable during downward movement of the receiver without any displacement of the interponent or actuation of the switch 385. The purpose of the control switch 385 will become apparent as this description progresses.

In the running description of the operation of the apparatus which is to follow it will become apparent that the valve 272 best shown in Figures 1b, 21, 23 and 39 and which controls the package receiver is manually actuated to effect a lifting of the receiver and is automatically actuated or tripped by ram movement, as shown in Figure 21, to permit the lowering of said receiver. Before proceeding with the summary description of the operation it should be explained that the various actuator cylinders have the flow of pressure fluid thereinto and therefrom controlled by electrically actuated valves. The platform lifting cylinder 80 of Figure 1, the long layer gate actuating cylinder 112 and the short layer gate actuating cylinder 110 of Figure 2, the tier sheet drop controlling cylinder 149 of Figures 9 and 10, the shaft oscillating cylinder 72 of Figures 2, 12 and 16, the #1 ram actuating cylinder 203 of Figures 1, 2 and 4, the vertical cylinder 253, and the horizontal cylinder 261 of the #2 ram, shown in Figures 1a, 3, 19 and 20, and the vertical cylinder 304 of the #3 ram, shown in Figures 1a, 3, 19 and 20 are controlled by four-way valves. A sample, somewhat diagrammatic illustration of such a four-way valve is provided in Figure 37, and it is believed this will suitably support the description of all of the cylinder operations controlled by four-way valves as aforesaid.

In the example four-way valve illustration in Figure 37 the casing 389 is equipped with an intermediate pressure fluid inlet port 390 which is connected with a suitable source of pressure fluid (not shown) through a supply duct 391. Endwise toward one end from the inlet port 390 the casing is equipped with a delivery and return port 392, and a similar delivery and return port 393 is provided toward the other end of the casing or to the other side of said inlet port 390. The ports 392 and 393 are to be connected by ducts 394 and 395 respectively to the head and rod ends of the particular actuator cylinder to be controlled by the valve. Inwardly projecting, axially spaced annuli divide the interior of the casing into a central annular pressure chamber 396, an annular flow chamber 397 communicating with the port 392, and an annular flow chamber 398 communicating with the port 393. The longitudinally reciprocable valve plunger 399 is equipped with two longitudinally spaced lands 400 so dimensioned and placed that they would simultaneously traverse and close both chambers 397 and 398 if the plunger were centered in the casing, and when moved to one end or the other would connect one said flow chamber 397 or 398 and its associated cylinder connecting duct to atmosphere and the other of said flow chamber and duct sets to the pressure chamber 396 and the connected fluid pressure supply, thereby to direct pressure fluid into a selected end of the connected actuator cylinder and exhaust fluid from the other end thereof. The valve plunger 399 is connected at one end to the reciprocable core of a solenoid 401, and at its other end to the reciprocable core of a solenoid 402. It will be readily apparent that by properly energizing and deenergizing the

solenoids the desired shifting of the valve plunger can be effected.

The horizontal cylinder 312 of the #3 ram, shown in Figures 1a, 3, 19 and 20, is controlled by two three-way valves because it is desirable at times to simultaneously open both ends of the cylinder to atmosphere. A sample, diagrammatic illustration of this control arrangement is provided in Figure 38.

In the example three-way valve illustration in Figure 38 the valves 403 and 404 may be of identical construction, and each may take the same form as the valve shown in 37 but have one of its delivery and return ports plugged as at 405 so that the remaining port and flow chamber alone will be effective to control the flow of pressure fluid to, and the return and exhausting of pressure fluid from, an end of the connected #3 ram cylinder 312. A common supply line 406 supplies pressure fluid to both valves, the delivery and return port of one valve is connected by a duct 407 with one end of the cylinder 312 and the delivery and return port of the other valve is connected by a duct 408 with the other end of said cylinder. The plunger 409 of the valve 403 is connected at one end to the reciprocable core of a solenoid 410, and at its other end to the reciprocable core of a solenoid 411. The plunger of the other valve is similarly connected with the actuating solenoids 412 and 413. It will be apparent by reference to Figure 38 that when the solenoids 411 and 412 are effectively energized to position the respective valve plungers as shown, pressure fluid will be directed into the rod end of the cylinder 312 and exhausted from the head end of said cylinder, and when the solenoids 410 and 413 are effectively energized, pressure fluid will be directed into the head end of the cylinder 312 and exhausted from the rod end thereof. It will also be apparent that by effectively energizing the solenoids 410 and 412 simultaneously, both ends of the cylinder 312 can be opened to atmosphere so that the #3 ram can move with the package complement of cans as it is being pushed by the #1 ram.

As a part of the control means for electrically controlling the valve associated with the tier sheet feed actuator cylinder 149 of Figure 9 there are included a control switch 414 disposed to be engaged by an actuator 415 movable with the platform sleeve 25 each time the platform reaches the upper limit of its travel, as shown in Figure 42, and a ratchet sequence relay means best shown in Figure 43. This relay means comprises a solenoid 416 to the reciprocable core of which is connected a pawl 417 effective each time the solenoid is energized to impart a step movement to the ratchet rotor 418 with which a three point cam 419 is movable. The points of the cam are engageable with the spring actuated lever 420 overlying the plunger of a double throw switch 421. It is to be understood that each time one of the flats of the cam 419 comes opposite the member 420 it will free it to move upwardly and clear the switch plunger and allow the switch contacter 422 to engage one contact with which it is normally engageable, and each time one of the cam points comes against the member 420 it will force it against the switch plunger and move the switch contacter 422 into engagement with the other contact of the switch. Thus the control circuits will be closed alternately through first one and then the other of the two contacts of the switch 421 on successive arrivals of the platform at the upper limit of its travel to bring out the desired shifting of the plunger 148 of the cylinder 149 first in one direction and then in the other to deliver the tier sheets selectively from the guides as shown in Figure 8.

It will be understood that as in the case of the sleeve-carried actuator 87 which is engageable with the switch 89, the actuator 415 carried by the sleeve 25 is engageable with the switch 414 just before said sleeve engages and is stopped by the stop collar 423 on the column 21 during each elevation of the platform.

In Figures 44 and 45 other control switches are shown, and these are actuated by movement of the #1 ram for purposes to be described hereinafter.

The switch 424 of Figure 44 is supported on a bracket 5 adjacent a cylinder 426 which is supported at 427 on the bars 205 which support the ram actuator cylinder 203, and the piston 428 slideable in the cylinder 426 has a rod 429 projecting therefrom through the rod end of the cylinder and connected at 430 with the #1 ram head 201 to move therewith. The actuator 431 of the switch 424 projects into the cylinder 426 through an opening 432 therein so placed that the piston 428 will come opposite said hole whenever the ram head 201 has been fully projected to the packaging station Y and will engage the actuator 431 and actuate the switch.

The switch 433 of Figure 45 is supported on a bracket 434 extending from the platform, and an actuator 435 overlies the plunger of the switch and is pivotally mounted on said bracket. An actuator 436 is attached at 437 20 on the ram head 201, and the knee joint mounted finger 438 thereof is disposed to momentarily depress and then release the actuator 435 each time the ram head is moving into its fully retracted position shown in Figure 45. However, because of the pivotal knee joint mounting of the finger 438 it will swing ineffectively in moving over the actuator 435 on each projection of the ram head toward the packaging station without any effect on the control circuit.

Operation

30 In describing the operation of the machine reference will be made principally to the cross line wiring diagram Figure 49, but also to other figures, and it will be assumed that the platform 32 is moving to the upper limit of its travel preparatory to receiving the first layer of cans in a new loading cycle. As the platform reaches the upper limit of its travel the actuator 415 of Figure 42 engages the switch 414 and brings about an energizing of the ratchet sequence relay solenoid 416 to position the cam 419 for controlling the switch 421 to energize one or the other of the solenoid coils 439 or 440 of the valve controlling the tier sheet depositing cylinder 149 of Figures 8, 9 and 10 in the manner previously described to shift the vanes 144 and drop the previously held tier sheets onto the platform.

45 At the same time the actuator 87 engages the double pole double throw switch 89 to accomplish two things. See Figures 12 and 49. One accomplishment is to energize the coil 441 of the solenoid effective to so position the valve controlling the platform lifting cylinder 80 of Figure 1 as to cut off the pressure fluid supply to the lower end thereof and open the same to atmosphere, thus removing the platform lifting force and allowing the action of gravity to become effective. The second accomplishment is to energize the starter coil 442 and cause the motor 16 of Figure 2 to impart movement to the can driving belts 12. This driving of the belts will be caused to continue until the platform again moves down step-by-step to the lower limit of its travel because of the provision of the interlock 443 which holds the starter coil 442 energized after the switch 89 is opened by the lowering of the platform out of contact therewith.

50 As the platform sleeve 25 engages the stop collar 423 on the column 21 the platform pawl 53 will have cleared the top stop 76 and dropped to rest thereon and place the platform floor 32 in position to receive the first layer of cans. The weight of the platform on the shaft 59 overcomes the lifting force of the spring 63 and will bring about a closing of the switch 66 shown in detail in Figure 12 and diagrammatically in Figure 49. This serves to energize the coils 444 and 445 of the valves controlling the gate actuating cylinders 110 and 112 and which are effective to lift said gates, thereby to open and then closed gates, namely the long layer gates 95. Compare Figures 6 and 5. This will allow can rows to run

in against the lowermost stop rail 40 and make up a long layer of cans. As each row making up said long layer becomes filled it will lift the respective actuator 120 and bring about a closing of the respective switch 119 in the manner illustrated in Figure 6, and when all rows are filled all switches 119 will have been closed and the control circuit will be completed through the selector switch 93 and energize the coil 446 of the solenoid which is effective to position the valve controlling the long layer gate actuating cylinder 112 to close the gates 95. See Figures 2, 6 and 15.

As the long layer gates 95 move to the fully closed position the switch 127 of Figure 2 will be closed, energizing the coil 447 effective to shift the valve associated with the shaft oscillating cylinder 72 of Figures 2, 12 and 16 in a direction for bringing about an oscillation of the shaft in a counterclockwise direction and withdrawing the support of the platform by the uppermost stop 76 to allow the platform to move down one step.

The platform now drops by gravity to the next lower stop 76. As the cans move down out of contact with the switch actuators 120 the series circuit through the switches 119 is broken. This leaves the long layer gates 95 closed but deenergizes the previously mentioned coil 446.

It will be apparent that as soon as the weight of the platform is removed from the indexing shaft 59 by the removal of a supporting stop 76 by oscillation of said shaft and the falling of the platform, the spring 63 of Figure 12 moves the shaft upward and actuates the switch 66 to break the previously closed gate control circuit. This deenergized the previously mentioned solenoid coils 444 and 445 so that reverse movement could be imparted to the gates. When the platform has reached the next indexing or lowering stop its weight again pushes the shaft 59 down against the spring 63 and closes the switch 66. This closes the circuit through both before mentioned coils 445 and 444 effective to shift the valves controlling the gate actuating cylinders 110 and 112 to lift or open the gates 95 and 96, and whichever gate set is lowered will be lifted or opened to permit can rows to run onto the platform, it being remembered that after the laying of the first layer of cans, each successively laid layer runs in directly onto and over a previously laid layer.

In order to permit either gate set 95 or 96 to be lowered or closed while the switch 66 is closed, relays 448 and 449 are connected in the circuits including the switch 66 and the controls for the valves associated with the gate operating air cylinders 110 and 112. The coil of the relay 448 is in parallel with the closing coil 446 of the valve which controls the long layer gate actuator cylinder 112, and the coil of the relay 449 is in parallel with the closing coil 450 of the valve which controls the short layer gate actuator cylinder 110, so that when either valve is actuated to close a gate set, the normally closed contactors 451 and 452, respectively, of the relays 448 and 449 will break the circuit through the switch 66 and the opening coils 444 and 445 which, when effective, serve to shift the valves controlling the gate cylinders 110 and 112 so as to bring about a lifting or opening of the gates. This permits the gates to be closed when the circuits through the series connected switches 119 or 122 require it. This control arrangement will be referred to again hereinafter, in greater detail.

As soon as the cylinder 72 has oscillated the shaft 59 and the platform has moved part-way down, the switches 119 or 122 are opened in the manner previously stated, by the falling away of the cans from the switch actuators, and the relay 448 or 449 is cut out, thus restoring a circuit through the switch 66 and the opening coils 444 and 445 of the valve controls for the cylinders 110 and 112. When the switch 66 is closed by weight of the platform the gates will open and permit the running in of can rows to form the second layer of cans.

The second layer of cans is a short layer. The can

rows will lift the actuators 123, and when all rows are full, will close all of the series connected switches 122 and energize the closing coil 450 of the valve associated with the actuator cylinder 110 to cause said cylinder to lower or close the short layer gates 96.

As the gates 96 are moved to the fully closed or lowered position, the switch 126 of Figures 2 and 18 is actuated to complete the circuit through the coil 453 effective to shift the valve associated with the shaft oscillating cylinder 72 of Figures 2, 12 and 16 in a direction for bringing about an oscillation of the shaft in a clockwise direction and withdrawal of the support of the platform by the second stop 76 to allow the platform to move down another step. The platform now drops down onto the third stop 76 ready to receive the third layer of cans.

In order to make it possible to close the short layer gates 96 while the weight of the platform is holding the switch 66 closed, prior to dropping the platform to the level for receiving the third row of cans it is necessary to interpose the coil of the relay 449 in the circuit with the series connected switches 122 and in parallel with the closing coil 450 of the valve that controls the short layer gate operating cylinder 110. As before stated, the contact points 452 of the relay 449 are normally closed and are in series with the switch 66 and the previously mentioned opening coils 444 and 445 of the valves which control both the short and long layer gate set operating cylinders 110 and 112. It will now be clear that as the series circuit through the switches 122 is closed there will

be a momentary flow of current through the closing coil 450 of the valve associated with the short layer gate actuating cylinder 110 while there is current maintained on the opening coil 445 of the same valve. For an instant the valve will not be moved because said opening coil remains energized. However, current passing through the coil of the rapid acting relay 449 will immediately open the contacts 452 which breaks the circuit through the switch 66 and the opening coils 444 and 445 of both valves controlling the long and short layer gate actuator cylinders 112 and 110. The breaking of the circuit through these coils enables the closing coil 450 for the short layer gates to take over and bring about a closing of the short layer gates 96.

As soon as the platform starts its downward movement after receiving the second layer of cans, the cans will move out of contact with the actuators of the switches 122 and the series circuit will be broken and the relay 449 deenergized. This restores the circuit through the switch 66 and the opening coil 445 so that when the platform again comes to rest on the third column stop an opening of the short layer gates will be effected to permit the third layer of cans to run onto the platform directly onto and over the cans of the second layer thereon, this third layer of cans being a long layer.

In order to make it possible to close the long layer gates 95 through the series connected switches 119, prior to dropping of the platform after the running in of the third layer of cans, and while the weight of the elevator is holding the circuit through the switch 66 and the opening coils 444 and 445 of the valves associated with the actuator cylinders 110 and 112 for both gate sets 96 and 95 closed, it is necessary to interpose the coil of the relay 448 in series with the switches 119 and in parallel with the closing coil 446 of the valve that controls the long layer gate actuating cylinder 112. The normally closed contact points 451 of the relay 448 are in series with the switch 66 and the coils 444 and 445 that bring about the opening of the long and short layer gates. It will now be clear that as the series circuit through the switches 119 is closed there will be a momentary flow of current through the closing coil 446 of the valve associated with the long layer gate actuating cylinder 112 while there is current maintained on the opening coil 444 of the same valve. For an instant the valve will not be moved because the opening coil 444 remains energized. However,

current passing through the coil of the rapid acting relay 448 immediately effects an opening of the contacts 451 and breaks the circuit through the switch 66 and both opening coils 444 and 445. The breaking of the circuit through these coils enables the closing coil 446 for the long layer gate control to take over and bring about a closing of the long layer gates 95.

The sequence described above in connection with the laying of the first three layers is repeated until the whole seven layers have been laid in staggered and nested relation.

When the indexing shaft 59 is oscillated to lower the platform after the seventh or last layer has been laid, the platform drops down to the unloading position shown in Figures 2 and 12. It will be noted that in this position the weight of the platform does not rest on the indexing shaft 59 but rather on the stop collar 79, and the switch 66 remains open.

At this point the double pole, double throw switch 88 is actuated by the platform 32 as it reaches its lower limit. See actuator 86 in Figure 12 and also Figure 27. This switch performs two functions. It breaks the circuit through the coil 442 and stops the motor 16 which drives the can driving belts 12 of Figure 2. It also phases the stop or indexing shaft 59 to bring it into proper position to support the platform to receive the first layer of cans in a new loading cycle. This requires an extra indexing movement of the shaft 59. This is accomplished through the agency of the relay generally designated 454. This relay carries three sets of contactors. One set 455, shunted around the switch 126 and normally open, is in series with the coil 453 which is effective in the manner previously described for bringing about a clockwise oscillation of the indexing shaft 59. Another set of said contactors 456, normally closed, is in series with the coil 447 which is effective in the manner previously described for bringing about an indexing of the shaft in a counterclockwise direction. The third set of contactors 457, normally open, constitutes a holding circuit for the coil 458 of the relay 454. The phasing of the shaft is brought about when the coil 458 of the relay is energized by the closing of the switch 88 which in turn closes the contacts 455 and energizes the solenoid 453 of the valve controlling the shaft indexing cylinder 72 and which is effective to bring about a clockwise movement of the indexing shaft 59. At the same time the normally closed contacts 456 are opened, preventing any possibility of current being on the opposing solenoid 447 of the valve that controls oscillation of the indexing shaft 59. The coil 458 of the relay 454 is maintained energized through the contacts 457 after the switch 88 has been released by elevation of the platform.

The switch 88 is shown in Figure 49 in its normal position, the position it will assume when the platform is elevated out of contact therewith.

In order to discharge the assembled and arranged package complement of cans from the platform 32 to the packaging station, the push button 459 is manually actuated. See Figure 49. At this time the #3 ram is in its lowered position and the horizontal sleeve 299 is stopped in its intermediate position against the lowered latch 323. See Figures 27 and 41. The actuation of the switch 459 energizes the solenoid coil 325 through the limit switch 460 which is closed by the lowering of the platform to its fully lowered position, and this serves to lift the latch 323 to make it possible for the stop 322 to pass under the latch during movement of the #3 ram 289 from the position shown in Figure 27 to the position shown in Figure 28 in which it is disposed in close proximity to the arranged package complement of cans on the platform 32. The switch 460 being connected in series in the solenoid control circuit referred to and in position for being closed by the platform in its fully lowered position makes it impossible to lift the

latch 323 unless the platform has been fully lowered. This final movement of the #3 ram to the position illustrated in Figure 28 is limited by the stops 318, 319, and as the ram is thus brought to rest it actuates the switch 330 as shown in Figures 19 and 28. See also Figure 49.

This actuation of the switch 330 closes a circuit through the valve coil 461 controlling the #1 ram cylinder 203 to move said ram for pushing the package complement of assembled and arranged cans from the platform 32 to the packaging station Y. The switch 330 also serves to energize the relay 462 having the contact points 463 and 464 to energize the coils 410 and 412 effective to place the #3 ram control valves of Figure 38 for opening the horizontal cylinder 312 to atmosphere at both ends. This permits the #3 ram 289 to move freely in contact with the cans and pushed by the #1 ram 201 while the cans are being transferred to the packaging station. See Figures 29 and 49.

Upon reaching the end of projection toward the packaging station the #1 ram 201 actuates the limit switch 424 in the manner shown in Figures 29 and 44. See also Figure 49. This switch energizes the coil 465 of the air valve that controls the vertical #2 ram cylinder 253 to cause said ram to move down. The #2 ram 236 moves down into position behind the package complement of cans at the packaging station as shown in Figure 30, it being understood that at this time the upright rods 210 and 238 of the #1 and #2 ram heads 201 and 236 are interfitted in approximately the same vertical plane but with the #2 ram head rods spaced slightly away from the cans and the end closure tier sheet contacted by the #1 ram head. See Figure 47. On approaching the lower limit of its travel the #2 ram 236, through actuator 257, momentarily actuates the switch 258 which energizes the coil 466 which is effective to adjust the control valve associated with the #1 ram cylinder 203 so as to bring about a retraction of the #1 ram 201 as shown in Figure 31. See also Figures 49 and 20. This closing of the switch 258 also causes the #3 ram 289 to move slightly to the left as viewed in Figure 31 to take up slack and hold the cans against the now effective #2 ram 236. This is accomplished through the relay coil 467 that operates the contactors 468 and 469. The actuation of the contactors 469 serves to energize the coil 411 of the valve 403 of Figure 38 effective to cause the #3 ram 289 to move to the left. The actuation of the contactors 468 serves no purpose at this particular time. The purpose for the actuation of the contactors will be described hereinafter.

As the #1 ram 201 approaches the limit of its retraction, as shown in Figure 31, it momentarily actuates the switch 433 of Figure 45 and energizes the coil 470 of the air valve controlling the cylinder 80 to direct air into the rod end of said cylinder and bring about a lifting of the platform 32 to start a new can arranging cycle while the packaging of the package complement of cans transferred to the packaging station is taking place. See also Figure 49.

Assuming now that a freshly glued wrapper has been placed in the holder 221 of Figures 1a and 3, by hand or by the machine of the previously mentioned copending application for patent, the operator can now proceed to apply the wrapper about the cans placed at the packaging station and held in place between the #2 and #3 rams 236 and 289 as shown in Figure 31. It will be recalled that these ram heads are offset inwardly, or toward each other, so that the marginal end edges of the wrapper when formed into a tube about the package complement of cans will extend marginal edge fold distances beyond the respective ends of the package complement of cans. See Figure 48. The operator first grasps the advance end of the wrapper and brings it up between the clamp 226 and the back plate 224 and steps on the treadle 230 to apply the clamp to grip the wrapper

end. See Figures 1a and 3. He then reaches over and grasps the trailing end of the wrapper and brings it over and presses this glued edge against the wrapper end extending upwardly above the clamp 226 and forms a sealed side seam. The clamp can then be released by removing pressure from the treadle 230. The bottom marginal edge at the right-hand end of the package is then folded upwardly and sealed against the tier sheet which is disposed at the end of the package and held in place by the #3 ram 289, then the top marginal edge is folded in and sealed, followed by the folding and sealing of the side edges. This infolding of the marginal edges of the wrapper is permitted by the inward spacing of the perimeter of the #3 ram head. See Figure 3. This completes the partial sealing of the package at the packaging station Y, and the package is now ready to be shifted to the final sealing station Z.

The operator next manipulates the handle 275 to open the valve 272 of Figures 21, 23 and 39 to direct air into the lower end of the receiver actuator cylinder 369 to lift the receiver 351 from the position shown in Figures 1a and 1b and Figures 27 through 31 to the position shown in Figure 24 and in Figures 32 through 34. As the receiver starts upward away from its fully lowered position, the actuator 388 of Figure 24 effects a momentary closing of the switch 385. See also Figure 49. The closing of this switch energizes the coil 471 of the valve effective to direct air into the vertical cylinder 304 to lift the #3 ram 289 as shown in Figure 33. The switch 385 also closes a circuit through the coil 472 of a relay having contactors 473 and 474. The contactors 474 serve to energize the coil 413 of the air valve 404 which causes the #3 ram 289 to move to the right. The other contactors 473 serve to energize the coil 410 effective to adjust the valve for opening the other end of the #3 ram cylinder 312 to atmosphere. The movement of the #3 ram 289 to the right at this time is slight and limited by engagement of the stop 317 with the abutment 320. See Figures 19 and 19a. Because of the fact that less effort is required to move the #3 ram horizontally than to move it vertically, the horizontal movement will take place in advance of the lifting of the ram, and in this manner movement of the ram out of contact with the sealed end of the package is assured before any upward movement which might tear the package can take place.

The #3 ram 289 moves to the upper limit of its travel and the actuator 309 engages and closes the switch 333. See Figures 20, 33 and 49. This serves to energize the coil 475 of the valve associated with the horizontal cylinder 261 of the #2 ram 236 so as to cause said ram to move to the right. See Figure 34. At the same instant the coil of the relay 476 that carries the contactors 477 and 478 is energized. The contactors 477 serve to energize the coil 412 that brings about a communication of the head end of the horizontal #3 ram cylinder 312 to atmosphere, and the contactors 478 serve to energize the coil 411 that brings about an application of pressure fluid to the rod end of said cylinder 312 to move the #3 ram to the left. See Figure 34. In moving to the left, the #3 ram passes the #2 ram 236 which is moving to the right to push the can package into the receiver 351. The #3 ram 289 comes to rest, as shown in Figure 34, against the intermediate stop latch 323 shown in Figures 27 and 40, the ram being still elevated and with air still on the horizontal cylinder 312, the velocity of movement of the ram being checked by the check means 339, 341 shown in Figures 1a and 20.

The limit switch 328 of Figures 1b, 19b and 49 is in series with the receiver movement actuated switch 385 and is actuated by the member 316 on the sleeve 299 when the #3 ram 289 has reached the right-hand travel limit. See Figure 32. This control interlock prevents the switch 385 from establishing circuits except when the #3 ram is at its right-hand travel limit. At times it may be desirable to raise or lower the receiver 351 manually

when the rams #2 and #3 rams 236 and 289 are in their left-hand positions. The purpose of the interlock switch 328 is to permit this to be done without bringing about undesired operation of said rams.

5 Just before the package of cans is bottomed in the receiver 351 by the #2 ram 236 as shown in Figure 34 the rod 267 movable with the sleeve 245 engages the latch member 277 as shown in Figure 21 and trips the latch 280, allowing the spring loaded valve plunger 273 of the valve 272 to move downwardly as viewed in Figure 39 and bring about an exhausting of air from the lower end of the cylinder 369 to permit lowering of the receiver 351. The bleed port 373 at the upper end of the cylinder 369 serves to cushion movement of the receiver in its upward movement, as before described, and will also retain a certain amount of air in the upper end of the cylinder. This trapped air will be effective as the latch 280 is tripped and air is released from the lower end of the cylinder 369 to expand and aid the #2 ram in pushing the receiver as the package is finally bottomed therein and the receiver is moving over the hump between the horizontal and upright positions thereof. Compare Figures 24, 35 and 36. Initial movement of the receiver along the horizontal track portions 348 serves 10 to remove the trailing marginal edge portions of the wrapper from beneath the delivery end portions of the bottom slats 217 of the form 215. As the receiver 351 starts down the incline 350, and while the trailing end of the package is still in close proximity to the #2 ram 236, the package is tilted slightly to clear said ram as shown in Figure 35 so that the same can be lifted without tearing the trailing marginal edges of the wrapper, and also to place the trailing tier of cans and the engaging tier sheet at an inclination to the vertical so that 15 there will be no tendency for them to fall away from the remainder of the package.

The receiver 351 now continues its downward movement, coming to rest in the position shown in Figures 1a, 1b and 36, being cushioned in its final lowering stage by 20 the check means 379 as well as the before-mentioned bleed port 373. While the receiver is in this position the operator completes the sealing thereof by closing and sealing the upwardly presented end, and then the package is rolled out of the receiver over the bottom another package complement of cans will have been arranged on the platform ready to be shifted from the platform 32 to the packaging station Y, or in other words, to the position in the form 215 shown in dot and dash line phantom in Figure 1a.

It is to be noted that the contactor points 468 of the relay 467 are in series with the coil 412 of the air valve associated with the #3 ram cylinder 312 and which when energized is effective to bring about atmospheric communication into the the head end of said cylinder. This is to assure that under all conditions the communication to atmosphere will be assured whenever the relay 467 is energized. See Figure 49.

Under certain conditions it is desirable to be able to bring about some of the machine functions manually. For example, when it is necessary to discharge from the platform 32 a partially completed package complement of cans, as may happen at the end of a run of cans having certain specifications. It will be apparent from the foregoing disclosure that unless cans are available in the runways the platform will not continue downward but will remain stopped in some intermediate position. To bring it down to the unloading position, the manually operable switch 482 may be utilized. This is a selector switch movable to one position to condition the machine for automatic handling, and to another position for conditioning the machine for manual handling. The switch is shown in the automatic control position in Figure 49. When moved to its other or manual control position the switch makes the push buttons 483, 484, 485 and 486 operative. The push button switch 483 bypasses the switches 93 and the series connected switches 119 and makes it possible to control the closing of the long layer gates 95 manually. The push button switch 484 bypasses the switch 66 and relay contacts 452 and 451 and makes it possible to manually control the opening of both sets of gates 95 and 96. The push button switch 485 bypasses the switch 126 and the relay contactors 455 which are in parallel with the switch 126 and makes it possible to manually control the indexing of the stop shaft 59 in a clockwise direction. The push button switch 486 bypasses the switch 127 and the relay contactors 456 and makes it possible to manually control the indexing of the stop shaft in a counterclockwise direction.

In order to assure that the machine can be started at any time with assurance that the same will commence operation properly regardless of the position in which the machine parts may have been left at the end of the preceding operation, the following means are provided. It will be noted that power is brought into the machine as a whole through the three-phase power lines 487 with which the belt driving motor 16 is connected as shown in Figure 49, and also the control transformer 488. The transformer 488 supplies one hundred and ten volt current to the control circuit. In series with this control circuit are the contactors 489 of a relay also including contactors 490 and the coil 491. When the contactors 489 are open the whole control circuit is dead. When it is desired to start the operation of the machine, the starter button 492 is pressed, and assuming that the disconnect switch 493 has been closed, current will flow through the coil 491 of said relay from the secondary of the transformer 488. This will close a circuit through the contactors 489 and 490 of the relay, making the whole control circuit alive. The button 492 and the switches 494 and 495 are mechanically connected so that actuation of said button will cause all to move in unison. The switch 494 is a normally closed switch connected in series with the valve coil 453 which controls clockwise oscillation of the stop shaft in the manner previously described, and when opened by pressing of said button will prevent oscillation of the stop shaft in a clockwise direction.

The switch 495 is a normally open switch connected in series with the relay coil 458, and when closed by the pressing of the button 492, it completes a circuit through

the coil 458, if the long layer gate control switch is closed, to effect an opening of the contactors 456 and prevent a counterclockwise indexing of the stop shaft 59. Should the long layer gate control switch 127 be open, the closing of the switch 495 will have no effect.

5 10 15 A switch 496 is provided and is connected in the control circuit for the can driving belts 12 through the control switch 38. In the event that the machine is stopped in an intermediate position prior to completion of a can arranging cycle, and then is restarted by a pressing of the button 492, the belt driving motor will fail to start. This motor can be started by pressing the button 496.

10 15 20 While example disclosures of the various steps of the method and the combinations and sub-combinations of apparatus for performing the method steps are made herein, it is to be understood that variations in said steps and apparatus may be made without departing from the spirit and scope of the invention as defined in the appended claims.

20 I claim:

1. The herein described method of arranging cans for packaging which comprises arranging a package complement of cans in the form of a multiple of superposed layers of cans each composed of a plurality of rows of cans, restraining the arranged can layers against movement in a direction perpendicular to the axes of the cans, applying pressure to the whole arranged package complement of superposed can layers in the direction of the axes of the cans and at at least one end of the package complement while confining said package complement against movement at its other end to take up spacing existing between opposing can ends thereby to compact the can arrangement and hold the cans against displacement, and while so confining and holding the cans, forming a snugly fitting tubular paper enclosure about the package complement of cans and folding in and sealing the projecting marginal portions of the paper to form a sealed package.

2. The herein described method of arranging cans for packaging which comprises arranging a package complement of cans in the form of a multiple of superposed layers of cans each composed of a plurality of rows of cans, restraining the arranged can layers against movement in a direction perpendicular to the axes of the cans, applying pressure to the whole arranged package complement of superposed can layers in the direction of the axes of the cans and at at least one end of the package complement while confining said package complement against movement at its other end to take up spacing existing between opposing can ends thereby to compact the can arrangement and hold the cans against displacement, and while so confining and holding the cans, placing an end closure sheet in position for lying against the cans at each end of the package complement, and while so confining and holding the cans, forming a snugly fitting tubular paper enclosure about the package complement of cans and said end closure sheets and folding in and sealing the projecting marginal portions of the paper against the end closure sheets to form a sealed package.

3. In apparatus of the character described, inclined gravity rollways over which to roll multiple can rows on their sides into horizontal parallel row relation to form can layers, a platform on which to receive an initially laid layer of cans, means for lowering the platform successive step distances to permit the rolling in of successive can layers directly onto and over previously laid can layers, and means for applying pressure to the cans of each of the successively laid layers of cans before and as the platform starts each downward step movement so as to prevent displacement of cans.

4. Apparatus as defined in claim 3, in which there are included vertically movable gate means operable in timed relation to the platform lowering steps to hold back the inrolling of cans as the platform is being lowered after completion of the inrolling of each successive layer of

cans, and wherein the pressure applying means comprises presser bars movable upwardly and downwardly with said gate means.

5. In apparatus of the character described, inclined gravity rollways over which to roll multiple can rows on their sides into horizontal parallel row relation to form can layers, a platform on which to receive an initially laid layer of cans, means for lowering the platform successive step distances to permit the rolling in of successive can layers directly onto and over previously laid can layers, driving belts opposed to and spaced from the rollways in position for engaging and applying driving contact to the peripheries of the inrolling cans to facilitate the rolling thereof first onto the platform and thereafter over the cans of the successively laid layers during each can package complement arranging cycle, means for again elevating the platform after the arrangement of each package complement of cans thereon, and means for discontinuing the operation of the belts each time the platform reaches its fully lowered position and for again initiating the belt operation each time the platform is returned to its elevated position.

6. In apparatus of the character described, means for rolling multiple can rows on their sides into horizontal parallel row relation to form can layers, a platform on which to receive an initially laid layer of cans, and means for lowering the platform successive step distances to permit the rolling in of successive can layers, means for placing tier sheets uprightly in parallel spaced relation on the platform and in position for having each row of the cans making up a layer roll into position between two tier sheets, with the platform, tier sheets and the successively laid can layers movable downwardly in unison, said tier sheet placing means including a pair of parallel guides for selectively receiving a tier sheet at each tier sheet placing position, and means shiftable each time the platform is elevated to its initial layer receiving position for closing the bottom of one guide of a pair to adapt it for holding a tier sheet therein and for opening the bottom of the other guide of the particular pair to release a tier sheet previously placed therein.

7. In apparatus of the character described, means for rolling multiple can rows on their sides into horizontal parallel row relation to form can layers, a platform on which to receive an initially laid layer of cans, and means for lowering the platform successive step distances to permit the rolling in of successive can layers, means for placing tier sheets uprightly in parallel spaced relation on the platform and in position for having each row of the cans making up a layer roll into position between two tier sheets, with the platform, tier sheets and the successively laid can layers movable downwardly in unison, said tier sheet placing means including a pair of parallel guides for selectively receiving a tier sheet at each tier sheet placing position, a vane associated with each guide pair and pivotally mounted in position for being swung back and forth to alternately open and close the bottoms of the guides of the pair, means for shifting the vanes, and means operable each time the platform is elevated to its initial layer receiving position for shifting the vanes for closing the bottom of one guide of each pair to adapt it for holding a tier sheet therein and for opening the bottom of the other guide of each pair to release a tier sheet previously placed therein.

8. In apparatus of the character described, means for rolling multiple can rows on their sides into horizontal parallel row relation to form can layers, a platform on which to receive an initially laid layer of cans, and means for lowering the platform successive step distances to permit the rolling in of successive can layers, means for placing tier sheets uprightly in parallel spaced relation on the platform and in position for having each row of the cans making up a layer roll into position between two tier sheets, with the platform, tier sheets and the successively laid can layers movable downwardly in unison, said tier sheet placing means including a guide for receiving

a tier sheet at each tier sheet placing position, means for feeding a web of tier sheet stock into each guide, and means operable in timed relation to the platform movement for severing tier sheet lengths of stock fed into said guides.

9. In apparatus of the character described, means for rolling multiple can rows on their sides into horizontal parallel row relation to form can layers, a platform on which to receive an initially laid layer of cans, and means for lowering the platform successive step distances to permit the rolling in of successive can layers, means for placing tier sheets uprightly in parallel spaced relation on the platform and in position for having each row of the cans making up a layer roll into position between two tier sheets, with the platform, tier sheets and the successively laid can layers movable downwardly in unison, said tier sheet placing means including a guide for receiving a tier sheet at each tier sheet placing position, means for feeding a web of tier sheet stock into each guide and including
10. separable grip roll pairs movable into and out of web feeding contact in timed relation to the platform movement, and means operable upon introduction of a predetermined length of tier sheet web stock into the guides for severing tier sheet lengths deposited in said guides.
15. 10. In apparatus of the character described, inclined gravity rollways over which to roll multiple can rows on their sides into horizontal parallel row relation to form can layers, a platform on which to receive an initially laid layer of cans, means for lowering the platform successive step distances to permit the rolling in of successive can layers directly onto and over previously laid can layers, thereby to arrange the can layers to constitute a package complement of cans, means providing a package complement packaging station, and reciprocable ram means operable each time the platform reaches its fully lowered position to push the arranged package complement of cans therefrom and place the same at said packaging station.
20. 11. In apparatus of the character described, inclined gravity rollways over which to roll multiple can rows on their sides into horizontal parallel row relation to form can layers, a platform on which to receive an initially laid layer of cans, and means for lowering the platform successive step distances to permit the rolling in of successive can layers directly onto and over previously laid can layers, said platform having an open side over which cans roll thereonto and being equipped at its opposite side with end stops spaced vertically can layer distances apart with the stops in alternated levels each spaced a can radius farther from said open side than the remaining stops so that can layers successively rolling onto the platform and over previously laid layers and against said stops will be arranged in alternately long and short layers and in staggered and nested relation as the platform and the stops thereon are moved downwardly step-by-step to receive said layers.
25. 12. Apparatus as defined in claim 11, in which there are also included two sets of alternately operable, vertically reciprocable gates for preventing inrolling of cans, said gate sets being placed at the level at which the cans roll into position over the platform and being spaced apart the distance of a can radius in the direction toward the end stops which are movable with the platform so as to be disposed for cooperation with said end stops in staggering and nesting the successively laid layers.
30. 13. Apparatus as defined in claim 11, in which there are also included two sets of alternately operable, vertically reciprocable gates for preventing inrolling of cans, said gate sets being placed at the level at which the cans roll into position over the platform and being spaced apart the distance of a can radius in the direction toward the end stops which are movable with the platform so as to be disposed for cooperation with said end stops in staggering and nesting the successively laid layers, and electrically controlled means for selecting the gate set

which is to be lowered to prevent continued inrolling of cans in accordance with the level to which the platform has been lowered, thereby to assure that a long layer controlling gate set will be placed in cooperative relation to platform carried long layer controlling end stops or that a short layer controlling gate set will be placed in cooperative relation to platform carried short layer controlling end stops at each downward step movement of the platform.

14. Apparatus as defined in claim 11, in which there are also included two sets of alternately operable, vertically reciprocable gates for preventing continued inrolling of cans, said gate sets being placed at the level at which the cans roll into position over the platform and being spaced apart the distance of a can radius in the direction toward the end stops which are movable with the platform so as to be disposed for cooperation with said end stops in staggering and nesting the successively laid layers, and means for assuring against lowering of a gate set until every row in the layer of cans being laid is full.

15. Apparatus as defined in claim 11, in which there are also included two sets of alternately operable, vertically reciprocable gates for preventing continued inrolling of cans, said gate sets being placed at the level at which the cans roll into position over the platform and being spaced apart the distance of a can radius in the direction toward the end stops which are movable with the platform so as to be disposed for cooperation with said end stops in staggering and nesting the successively laid layers, and means for assuring against lowering of a gate set until every row in the layer of cans being laid is full, said last-named means including a set of series connected switches, each switch in which series is actuatable by the positioning of a can against a long layer controlling end stop in the particular row, and a set of series connected switches each switch in which is actuatable by the positioning of a can against a short row controlling end stop in the particular row.

16. Apparatus as defined in claim 11, in which there are also included two sets of alternately operable, vertically reciprocable gates for preventing continued inrolling of cans, said gate sets being placed at the level at which the cans roll into position over the platform and being spaced apart the distance of a can radius in the direction toward the end stops which are movable with the platform so as to be disposed for cooperation with said end stops in staggering and nesting the successively laid layers, electrically controlled means for selecting the gate set which is to be lowered to prevent continued inrolling of cans in accordance with the level to which the platform has been lowered, thereby to assure that a long layer controlling gate set will be placed in cooperative relation to platform carried long layer controlling end stops or that a short layer controlling gate set will be placed in cooperative relation to platform carried short layer controlling end stops at each downward step movement of the platform, and means for assuring against lowering of a gate set until every row in the layer of cans being laid is full, said last-named means including a set of series connected switches, each switch in which series is actuatable by the positioning of a can against a long layer controlling end stop in the particular row, and a set of series connected switches each switch in which is actuatable by the positioning of a can against a short row controlling end stop in the particular row.

17. Apparatus as defined in claim 3, in which there are included vertically movable gate means operable in timed relation to the platform lowering steps to prevent continued inrolling of cans upon completion of the inrolling of each successive layer of cans, and wherein the pressure applying means comprises presser bars movable upwardly and downwardly with said gate means and spring-biased in a downward direction so that they can yield upwardly as they contact the cans of a layer during

the lowering of the gates and then follow downwardly with and apply yieldable pressure to said cans as they start their movement downward with the platform.

18. Apparatus as defined in claim 11, in which the short layer controlling end stops are mounted so that they can be shifted between projected effective and retracted ineffective positions, and wherein are provided means operable during lowering of the platform for shifting the shiftable end stops to their ineffective positions after they have served their function of placing the short layers and operable during the elevating of the platform for again replacing said shiftable end stops in their effective positions.

19. In apparatus of the character described, means for rolling multiple can rows on their sides into horizontal parallel row relation to form can layers, a platform on which to receive an initially laid layer of cans, means for lowering the platform successive step distances to permit the rolling in of successive can layers, thereby to arrange the can layers to constitute a package complement of cans, means providing a package complement packaging station, means providing a package sealing station, a first horizontally reciprocable ram, means for operating said first ram to project the same each time the platform is fully lowered to push the package complement of cans thereon from the platform into position for being enclosed in packaging paper, a second horizontally and vertically movable ram, and means for operating said second ram to first lower it into position behind a can package at the packaging station, then move the second ram horizontally to push the package to the sealing station, then elevate said second ram, and then retract the second ram horizontally to its initial position.

20. Apparatus as defined in claim 19, wherein the first and second rams have can complement engaging heads formed of parallel spaced uprights disposed so that the uprights of one ram head may interfit and pass between those of the other so that it is possible for the second ram to descend behind the can package complement while the first ram is in engagement therewith and for one said ram head to move in a horizontal direction relative to the other ram head with its head uprights passing through between the uprights of said other ram head.

21. Apparatus as defined in claim 19, wherein the first ram and the means for operating the same are mounted for movement upwardly and downwardly with the platform on which the can layers are arranged, thereby to always retain the intended cooperative relation of the platform and said first ram.

22. Apparatus as defined in claim 10, in which there are included means for preventing elevation of the platform if the ram means is not fully retracted, and means for preventing advancing of the ram means if the platform is not at its fully lowered position.

23. Apparatus as defined in claim 19, in which there are included means for preventing elevation of the platform if the first ram is not fully retracted, and means for preventing advancing of the first ram if the platform is not at its fully lowered position.

24. Apparatus as defined in claim 19, wherein there is included at the packaging station means for placing a paper wrapper in position for being snugly applied as an open-ended tube about a package complement of cans presented at the packaging station with said tube extending an end margin fold distance at each end beyond the cans of the package complement, the second ram being offset so that it can project into the end of the paper tube and against the end of the package complement of cans therein.

25. Apparatus as defined in claim 10, in which there are included another ram means and means for causing the same to move in cooperative relation to the first-mentioned ram means so that it will first move into close proximity to an arranged package complement of cans

backed up by said first-mentioned ram means, then move with said first-mentioned ram means during the movement of the cans to the packaging station, with the package complement of cans engaged at its ends between and held under control by said ram means.

26. Apparatus as defined in claim 19, wherein there are included a third ram and means for causing the same to move in cooperative relation to the first ram so that it will first move into close proximity to an arranged package complement of cans backed up by the first ram, then move with the first ram during the movement of the cans by said first ram to the packaging station, with the package complement of cans engaged at its ends between and held under control by said first and third rams.

27. Apparatus as defined in claim 19, wherein there is included at the packaging station means for placing a paper wrapper in position for being snugly applied as an open-ended tube about a package complement of cans presented at the packaging station with said tube extending an end margin fold distance at each end beyond the cans of the package complement, and wherein there are included a third ram and means for causing the same to move in cooperative relation to the first ram so that it will first move into close proximity to an arranged package complement of cans backed up by the first ram, then move with the first ram during the movement of the cans by said first ram to the packaging station, with the package complement of cans engaged at its ends between and held under control by said first and third rams, said second and third rams being offset toward each other so that they can project into the ends of the paper tube and against the ends of the package complement of cans therein.

28. Apparatus as defined in claim 19, wherein there is included at the packaging station means for placing a paper wrapper in position for being snugly applied as an open-ended tube about a package complement of cans presented at the packaging station with said tube extending an end margin fold distance at each end beyond the cans of the package complement, and wherein there are included a third ram and means for causing the same to move in cooperative relation to the first ram so that it will first move into close proximity to an arranged package complement of cans backed up by the first ram, then move with the first ram during the movement of the cans by said first ram to the packaging station, with the package complement of cans engaged at its ends between and held under control by said first and third rams, said second and third rams being offset toward each other so that they can project into the ends of the paper tube and against the ends of the package complement of cans therein, said third ram being shaped and dimensioned to leave a free space about four edges thereof when in engagement with an end of a package complement of cans, into which space the wrapper margins can be turned in completely sealing the end of the package at which the third ram is disposed.

29. Apparatus as defined in claim 19, wherein there is included at the packaging station means for placing a paper wrapper in position for being snugly applied as an open-ended tube about a package complement of cans presented at the packaging station with said tube extending an end margin fold distance at each end beyond the cans of the package complement, and wherein there are included a third ram and means for causing the same to move in cooperative relation to the first ram so that it will first move into close proximity to an arranged package complement of cans backed up by the first ram, then move with the first ram during the movement of the cans by said first ram to the packaging station, with the package complement of cans engaged at its ends between and held under control by said first and third rams, said second and third rams being offset toward each other so that they can project into the ends of the paper tube and

against the ends of the package complement of cans therein, said third ram being shaped and dimensioned to leave a free space about four edges thereof when in engagement with an end of a package complement of cans, into which space the wrapper margins can be turned in completely sealing the end of the package at which the third ram is disposed, and being movable horizontally away from the sealed package end and then upwardly out of the way, thereby to avoid scraping and tearing of the sealed end of the wrapper and free the package so that it can be discharged from the packaging station to the sealing station.

30. Apparatus as defined in claim 19, wherein there is included at the packaging station means for placing a paper wrapper in position for being snugly applied as an open-ended tube about a package complement of cans presented at the packaging station with said tube extending an end margin fold distance at each end beyond the cans of the package complement, said wrapper placing means including a form in which to receive the package complement of cans from the platform, said form being defined by side and bottom walls composed of parallel spaced slats providing openings which permit the cans to protrude into direct contact with the paper wrapper so as to provide a tight and compact package.

31. Apparatus as defined in claim 19, wherein there is included at the packaging station means for placing a paper wrapper in position for being snugly applied as an open-ended tube about a package complement of cans presented at the packaging station with said tube extending an end margin fold distance at each end beyond the cans of the package complement, said wrapper placing means including a form in which to receive the package complement of cans from the platform, said form being defined by side and bottom walls composed of parallel spaced slats providing openings which permit the cans to protrude into direct contact with the paper wrapper so as to provide a tight and compact package, and there also being included means for supporting the form defining walls cantilever fashion at their receiving ends so as to leave the discharge ends of the walls free and facilitate the discharging of packaged cans from the form.

32. Apparatus as defined in claim 19, wherein there is included at the packaging station means for placing a paper wrapper in position for being snugly applied as an open-ended tube about a package complement of cans presented at the packaging station with said tube extending an end margin fold distance at each end beyond the cans of the package complement, and wherein there are included a third ram and means for causing the same to move in cooperative relation to the first ram so that it will first move into close proximity to an arranged package complement of cans backed up by the first ram, then move with the first ram during the movement of the cans by said first ram to the packaging station, with the package complement of cans engaged at its ends between and held under control by said first and third rams, the second and third rams being offset toward each other so that they can project into the ends of the paper tube and against the ends of the package complement of cans therein, said third ram being shaped and dimensioned to leave a free space about four edges thereof when in engagement with an end of a package complement of cans, into which space the wrapper margins can be turned in completely sealing the end of the package at which the third ram is disposed, and there being provided at the sealing station a receiver into which a partially sealed package is pushed by the second ram, said receiver being shiftable between an elevated horizontal position in which to receive a package, and a lowered upright position in which the unsealed end of the package is upwardly disposed in position for facilitating the step of finally sealing the package.

33. Apparatus as defined in claim 19, wherein there

is included at the packaging station means for placing a paper wrapper in position for being snugly applied as an open-ended tube about a package complement of cans presented at the packaging station with said tube extending an end margin fold distance at each end beyond the cans of the package complement, and wherein there are included a third ram and means for causing the same to move in cooperative relation to the first ram so that it will first move into close proximity to an arranged package complement of cans backed up by the first ram, then move with the first ram during the movement of the cans by said first ram to the packaging station, with the package complement of cans engaged at its ends between and held under control by said first and third rams, the second and third rams being offset toward each other so that they can project into the ends of the paper tube and against the ends of the package complement of cans therein, said third ram being shaped and dimensioned to leave a free space about four edges thereof when in engagement with an end of a package complement of cans, into which space the wrapper margins can be turned in completely sealing the end of the package at which the third ram is disposed, and there being provided at the sealing station a receiver into which a partially sealed package is pushed by the second ram, said receiver being shiftable between an elevated horizontal position in which to receive a package, and a lowered upright position in which the unsealed end of the package is upwardly disposed in position for facilitating the step of finally sealing the package, and being U-shaped in vertical transverse section when in horizontal position and having an open end directed toward the packaging station, and a closed end directed away from said packaging station, and means for positioning the receiver in timed relation to the movements of the rams to receive the package pushed thereto by the second ram, the third ram being movable upwardly out of the way, and the second ram being then movable to discharge the package from the packaging station into the receiver.

34. Apparatus as defined in claim 19, wherein there is included at the packaging station means for placing a paper wrapper in position for being snugly applied as an open-ended tube about a package complement of cans presented at the packaging station with said tube extending an end margin fold distance at each end beyond the cans of the package complement, and wherein there are included a third ram and means for causing the same to move in cooperative relation to the first ram so that it will first move into close proximity to an arranged package complement of cans backed up by the first ram, then move with the first ram during the movement of the cans by said first ram to the packaging station, with the package complement of cans engaged at its ends between and held under control by said first and third rams, the second and third rams being offset toward each other so that they can project into the ends of the paper tube and against the ends of the package complement of cans therein, said third ram being shaped and dimensioned to leave a free space about four edges thereof when in engagement with an end of a package complement of cans, into which space the wrapper margins can be turned in completely sealing the end of the package at which the third ram is disposed, and there being provided at the sealing station a receiver into which a partially sealed package is pushed by the second ram, said receiver being shiftable between an elevated horizontal position in which to receive a package, and a lowered upright position in which the unsealed end of the package is upwardly disposed in position for facilitating the step of finally sealing the package, and having a bottom wall engaged by the sealed end of the package when the receiver is lowered and formed of rollers serving as a conveyor floor over which the package can be rolled with facility.

35. Apparatus as defined in claim 19, wherein there is included at the packaging station means for placing

a paper wrapper in position for being snugly applied as an open-ended tube about a package complement of cans presented at the packaging station with said tube extending an end margin fold distance at each end beyond the cans of the package complement, and wherein there are included a third ram and means for causing the same to move in cooperative relation to the first ram so that it will first move into close proximity to an arranged package complement of cans backed up by the first ram, then move with the first ram during the movement of the cans by said first ram to the packaging station, with the package complement of cans engaged at its ends between and held under control by said first and third rams, the second and third rams being offset toward each other so that they can project into the ends of the paper tube and against the ends of the package complement of cans therein, said third ram being shaped and dimensioned to leave a free space about four edges thereof when in engagement with an end of a package complement of cans, into which space the wrapper margins can be turned in completely sealing the end of the package at which the third ram is disposed, and there being provided at the sealing station a receiver into which a partially sealed package is pushed by the second ram, said receiver being shiftable between an elevated horizontal position in which to receive a package, and a lowered upright position in which the unsealed end of the package is upwardly disposed in position for facilitating the step of finally sealing the package, said receiver being tiltable slightly during the discharging of the package thereinto and before lowering thereof to clear the unsealed end of the package from the second ram so that the latter can be lifted without fouling and tearing the paper wrapper at said unsealed package end.

36. In apparatus of the character described, inclined gravity rollways over which to roll multiple can rows on their sides into horizontal parallel row relation to form can layers, a platform on which to receive an initially laid layer of cans, means for lowering the platform successive step distances to permit the rolling in of successive can layers, and means for elevating the platform to its initial layer receiving position after an arranged package complement of cans has been removed therefrom, said elevating means including fluid pressure actuated cylinder and piston means, and said lowering means comprising a stop member secured to and movable with the platform and vertically spaced platform level control stops engageable by the platform carried stop member and successively removable for permitting the platform to fall accurately determined step distances by gravity action.

37. In apparatus of the character described, means for rolling multiple can rows on their sides into horizontal parallel row relation to form can layers, a platform on which to receive an initially laid layer of cans, and means for lowering the platform successive step distances to permit the rolling in of successive can layers, said platform being carried by a long upright sleeve bearing slidable on a single column constituting the sole support for the platform so that all loads and bending stresses are carried by said single column, there being also provided a vertical guide and a fork projecting from the platform and slidably contacting said guide and serving to hold the platform against swinging about the axis of the column.

38. In apparatus of the character described, means for rolling multiple can rows on their sides into horizontal parallel row relation to form can layers, a platform on which to receive an initially laid layer of cans, means for lowering the platform successive step distances to permit the rolling in of successive can layers, and means for elevating the platform to its initial layer receiving position after an arranged package complement of cans has been removed therefrom, said elevating means including fluid pressure actuated cylinder and

piston means, and said lowering means comprising a stop movable with the platform and vertically spaced platform level control stops engageable by the platform carried stop member and successively removable for permitting the platform to fall accurately determined step distances by gravity action, said control stops projecting radially from a vertical shaft into position for being selectively engageable by the platform carried stop member, means also being provided for moving said shaft about its axis to selectively present said stop members.

39. In apparatus of the character described, means for rolling multiple can rows on their sides into horizontal parallel row relation to form can layers, a platform on which to receive an initially laid layer of cans, means for lowering the platform successive step distances to permit the rolling in of successive can layers, and means for elevating the platform to its initial layer receiving position after an arranged package complement of cans has been removed therefrom, said elevating means including fluid pressure actuated cylinder and piston means, and said lowering means comprising a stop movable with the platform and vertically spaced platform level control stops engageable by the platform carried stop member and successively removable for permitting the platform to fall accurately determined step distances by gravity action, said control stops projecting radially from a vertical shaft into position for being selectively engageable by the platform carried stop member and being arranged in two vertical columns spaced circumferentially about the shaft and with vertically aligned stops arranged in distinct columns so that the stops can be successively presented for stopping and supporting the platform falling by gravity action by oscillating the shaft back and forth to effectively place first one stop in one column and then the next lower stop in the other column and so on.

40. In apparatus of the character described, means for rolling multiple can rows on their sides into horizontal parallel row relation to form can layers, a platform on which to receive an initially laid layer of cans, means for lowering the platform successive step distances to permit the rolling in of successive can layers, and means for elevating the platform to its initial layer receiving position after an arranged package complement of cans has been removed therefrom, said elevating means including fluid pressure actuated cylinder and piston means, and said lowering means comprising a stop member movable with the platform and vertically spaced platform level control stops engageable by the platform carried stop and successively removable for permitting the platform to fall accurately determined step distances by gravity action, said control stops projecting radially from a vertical shaft into position for being selectively engageable by the platform carried stop, means also being provided for moving said shaft about its axis to selectively present said stop members, and there being included also fluid pressure cylinder means for cushioning each lowering step of the platform.

41. In apparatus of the character described, means for rolling multiple can rows on their sides into horizontal parallel row relation to form can layers, a platform on which to receive an initially laid layer of cans, means for lowering the platform successive step distances to permit rolling in of successive can layers, said platform having an open side over which cans roll thereonto and being equipped at its opposite side with end stops spaced vertically can layer distances apart with the stops in alternated levels each spaced a can radius farther from said open side than the remaining stops so that can layers successively rolling onto the platform and against said stops will be arranged in alternately long and short layers and in staggered and nested relation, two gate sets placed at the level at which the cans roll into position over the platform and spaced

apart the distance of a can radius in the direction toward the end stops, said gate sets being vertically reciprocable and alternately operable, air cylinder means for operating said gate sets, means for electrically controlling the gate set operating means and including a set of series connected switches each switch in which series is actuated by the positioning of a can against a long layer controlling end stop in the particular row and a set of series connected switches each switch in which is actuatable by the positioning of a can against a short row controlling end stop in a particular row so that the gates cannot be operated unless all rows in the long or short layers are full, said platform lowering means including an oscillatable shaft having rest stops thereon spaced platform step distances vertically to be successively effective to release the platform to let it fall by gravity and then intercept and support the platform, air cylinder means for oscillating the shaft and electrically controlled by means including a switch operable incidental to gate set movements so that lowering of the platform cannot precede proper closing of the gate sets.

42. Apparatus as defined in claim 41, in which the gate set operating air cylinder means actuate the gate sets through crank arms and the control circuit means controlling the lowering of the platform includes switch means operable by the crank arms during the final portion of the gate set lowering movement so that lowering of the platform cannot precede proper closing of the long or short gate sets.

43. Apparatus as defined in claim 41, in which there is included means for spring lifting the platform descent controlling shaft slightly each time the weight of the platform is removed by displacement of a platform supporting stop, and in which the gate set controlling circuit includes a switch which is closed each time the weight of the platform is supported on one of the shaft stops and opened each time the spring lifts the shaft.

44. Apparatus as defined in claim 41, in which the shaft carried platform descent controlling stops are so spaced as to drop the platform through layer depth steps incidental to the arranging of successive can layers, and then a longer step drop after the laying of the last layer so as to position the package complement of cans for being discharged from the platform, means also being included for assuring that a long layer will be laid at the commencement and also at the conclusion of each can package complement arranging cycle.

45. Apparatus as defined in claim 41, in which the shaft carried platform descent controlling stops are so spaced as to drop the platform through layer depth steps incidental to the arranging of successive can layers, and then a longer step drop after the laying of the last layer so as to position the package complement of cans for being discharged from the platform, means also being included for assuring that a long layer will be laid at the commencement and also at the conclusion of each can package complement arranging cycle, said last-named means including a phasing switch connected in the circuit controlling oscillation of the stop shaft and operable on the last long drop of the platform to bring about a turning of the shaft into proper phase.

46. In apparatus of the character described, a can layer supporting platform, means for feeding individual layers of cans onto the platform, means for lowering the platform step-by-step to receive the can layers and arrange them in superposed relation, means for elevating the platform to its initial layer receiving position after a package complement of cans has been arranged thereon and discharged therefrom, a packaging station, a sealing station, a reciprocable ram for moving a package complement of cans from the platform when lowered and placing the same at the packaging station for having an enclosing wrapper placed thereon, another ram for shifting the package from the packaging station to the sealing

station, and means for controlling the operation of the platform lowering and elevating means and the rams through a manually initiated automatically terminated cycle.

47. Apparatus as defined in claim 46, in which are included control devices for cooperatively timing the operation of the can feeding means, the platform lowering and elevating means and the rams so that the packaging of one package complement of cans can be accomplished at the packaging station while another package complement of cans is being assembled and arranged on the platform.

48. Apparatus as defined in claim 46, in which the controlling means includes a switch closed by the lowering of the platform to its fully lowered position so that the operating cycle cannot be manually initiated except when the platform is in its fully lowered position.

49. Apparatus as defined in claim 46, in which the controlling means includes switch means engaged by a part moving with the platform as it reaches its bottom limit and effective to initiate action of the ram which pushes the package complement of cans to the packaging station, switch means actuated by ram travel as said ram reaches the packaging station and effective to bring about a retraction of said ram, and devices effective as said ram is fully retracted to discontinue the ram movement and start the platform on its upward travel in preparation for another loading cycle.

50. In apparatus of the character described, a can layer supporting platform, means for feeding individual layers of cans onto the platform, means for lowering the platform step-by-step to receive the can layers and arrange them in superposed relation, means for elevating the platform to its initial layer receiving position after a package complement of cans has been arranged thereon and discharged therefrom, a packaging station, a sealing station, a reciprocable ram for moving a package complement of cans from the platform when lowered and placing the same at the packaging station for having an enclosing wrapper placed thereon, a second ram and means for imparting four-motion movement for moving downwardly into position behind a can package at the packaging station, and then forwardly to move the package to the sealing station, then upwardly and then back to its initial raised position, a third ram and means for controlling movement thereof for moving the same downwardly and then horizontally into position for engaging in advance of the package complement of cans, then with the cans while holding them under control in opposition to the first ram, then upwardly out of the way so that the second ram can push the package to the sealing station, and then back to its initial elevated position.

51. Apparatus as defined in claim 50, wherein there are included control devices including switch means effective to prevent lowering of the third ram into position opposite the first ram until after the second ram has moved its full limit in the direction for moving the package to the sealing station.

52. In apparatus of the character described, means for rolling multiple can rows on their sides into horizontal parallel row relation to form can layers, a platform on which to receive an initially laid layer of cans, means for lowering the platform successive step distances to permit the rolling in of successive can layers, means for placing tier sheets uprightly in parallel spaced relation on the platform and in position for having each row of the cans making up a layer roll into position between two tier sheets, with the platform, tier sheets and the successively laid can layers movable downwardly in unison, means providing a package complement packaging station, a reciprocable ram operable each time the platform reaches its fully lowered position to push the arranged package complement of cans therefrom and place the same at said packaging station, said platform having

upwardly movable floor sections extending transversely thereof with relation to the direction in which the cans roll onto the platform and longitudinally with relation to the direction in which the ram pushes the arranged package complement of cans and interposed tier sheets to the packaging station, said floor sections lying flat on the platform during the arranging of can layers thereon so that they will not interfere with the arranging of cans, and means being provided for moving the floor sections upwardly as the platform reaches its lower travel limit so as to lift the tier sheets above the platform.

53. Apparatus as defined in claim 52, in which there is provided a U-shaped form in which the package complement of cans is received at the packaging station, there being also included roller and track means for supporting the ram as it moves over the platform and into the form when pushing the package complement of cans from the platform to the packaging station.

54. In apparatus of the character described, means for rolling multiple can rows on their sides into horizontal parallel row relation to form can layers, a platform on which to receive an initially laid layer of cans, means for lowering the platform successive step distances to permit the rolling in of successive can layers, thereby to arrange the can layers to constitute a package complement of cans, means for placing on the platform two package end closure sheets for opposing the ends of the package complement of cans and for moving down with the platform and can layers as the latter are being arranged, upright restraining members for guiding said sheets and preventing falling thereof away from the ends of the can layers, means providing a package complement packaging station, a horizontally reciprocable ram, and means for operating said ram each time the platform is fully lowered to push the package complement of cans therefrom to the packaging station, at least one of said upright restraining members being swingably mounted to be displaceable by contact as the package complement of cans is being pushed to the packaging station.

55. In apparatus of the character described, means for rolling multiple can rows on their sides into horizontal parallel row relation to form can layers, a platform on which to receive an initially laid layer of cans, means for lowering the platform successive step distances to permit the rolling in of successive can layers, thereby to arrange the can layers to constitute a package complement of cans, means for placing on the platform two package end closure sheets for opposing the ends of the package complement of cans and for moving down with the platform and can layers as the latter are being arranged, upright restraining members for guiding said sheets and preventing falling thereof away from the ends of the can layers, means providing a package complement packaging station, a horizontally reciprocable ram, and means for operating said ram each time the platform is fully lowered to push the package complement of cans therefrom to the packaging station, said ram having a clearance therein permitting it to move freely past one said upright restraining member, and the other of said upright restraining members being swingably mounted to be displaceable by package complement contact as the package complement of cans is being pushed to the packaging station.

56. Apparatus as defined in claim 19, wherein there are included a third ram and means for causing the same to move in cooperative relation to the first ram so that it will first move into close proximity to an arranged package complement of cans backed up by the first ram, then move with the first ram during the movement of the cans by said first ram to the packaging station, with the package complement of cans engaged at its ends between and held under control by said first and third rams, said third ram moving means including control devices effective to present the third ram in opposition to the second ram before the latter is moved to push the pack-

age to the sealing station and to move the third ram a distance toward the second ram prior to the last-named movement of the second ram so as to compact the cans against the second ram before the package is moved to the sealing station.

57. Apparatus as defined in claim 19, wherein there is included at the packaging station means for placing a paper wrapper in position for being snugly applied as an open-ended tube about a package complement of cans presented at the packaging station with said tube extending an end margin fold distance at each end beyond the cans of the package complement, a third ram and means for moving the same in cooperative relation to the first ram so that it will first move into close proximity to an arranged package complement of cans backed up by the first ram, then move with the first ram during the movement of the cans by said first ram to the packaging station, with the package complement of cans engaged at its ends between and held under control by said first and third rams, said third ram moving means including control devices effective to present the third ram in opposition to the second ram before the latter is moved to push the package to the sealing station and to move the third ram a distance toward the second ram prior to the last-named movement of the second ram so as to compact the cans against the second ram before the package is moved to the sealing station, said third ram being shaped and dimensioned to leave a free space about four edges thereof when in engagement with an end of a package complement of cans, into which space the wrapper margins can be turned in completely sealing the end of the package at which the third ram is disposed.

58. In apparatus of the character described, a can layer supporting platform, means for feeding individual layers of cans onto the platform, means for lowering the platform step-by-step to receive the can layers and arrange them in superposed relation, means for elevating the platform to its initial layer receiving position after a package complement of cans has been arranged thereon and discharged therefrom, a packaging station, a sealing station, a reciprocable ram for moving a package complement of cans from the platform when lowered and placing the same at the packaging station for having an enclosing wrapper placed thereon, a second ram and means for imparting four-motion movement thereto for moving downwardly into position behind a can package complement of cans opposed by the first ram at the packaging station, then forwardly to move the package to the sealing station, then upwardly and then back to its initial raised position, a third ram and means for controlling movement thereof for moving the same downwardly and then horizontally into position for engaging in advance of the package complement of cans, then with the cans while holding them under control in opposition to the first ram, said third ram movement controlling means also including control devices effective to move the third ram a distance toward the second ram while opposing the same at the packaging station so as to compact the cans against the second ram before the package is moved to the sealing station, then forwardly and upwardly out of the way of the package before it is delivered at the sealing station.

59. Apparatus as defined in claim 19, wherein there is included at the packaging station means for placing a paper wrapper in position for being snugly applied as an open-ended tube about a package complement of cans presented at the packaging station with said tube extending an end margin fold distance at each end beyond the cans of the package complement, said wrapper placing means including a form in which to receive the package complement of cans from the platform, said form being U-shaped in vertical cross section with the sides and base portion of the U spaced apart to permit peripheral portions of cans to project into the spaces, and the sides of the U being dimensioned to permit cans at the ends

of the rows forming the uppermost layer in the package complement of cans to project at least slightly above said sides.

60. Apparatus as defined in claim 19, wherein there is included at the packaging station means for placing a paper wrapper in position for being snugly applied as an open-ended tube about a package complement of cans presented at the packaging station with said tube extending an end margin fold distance at each end beyond the cans of the package complement, said wrapper placing means including a form in which to receive the package complement of cans from the platform, said form being U-shaped in vertical cross section with the sides and base portion of the U spaced apart to permit peripheral portions of cans to project into the spaces, and the sides of the U being dimensioned to permit cans at the ends of the rows forming the uppermost layer in the package complement of cans to project at least slightly above said sides, and said form defining sides and base portion being supported cantilever fashion at their receiving ends so as to leave the discharge ends free and facilitate the discharging of packaged cans from the form.

61. Apparatus as defined in claim 52, in which there is provided a U-shaped form in which the package complement of cans is received at the packaging station and having longitudinal parallel spaced base members between which cans of the lowermost layer of each package complement of cans are confined, the upwardly movable floor sections of the platform when elevated serving to place the lower edges of the tier sheets at the level of the uppermost portions of said form base members and to center said tier sheets vertically with relation to the cross section of the package complement of cans, and said form base members serving to hold the tier sheets in said vertically centered position when moved thereover.

62. Apparatus as defined in claim 41, in which the shaft carried platform descent controlling stops are so spaced as to drop the platform through layer depth steps incidental to the arranging of successive can layers, and then a longer step drop after the laying of the last layer so as to position the package complement of cans for being discharged from the platform, means also being included for assuring that when an odd number of layers is arranged on the platform the lowermost and uppermost layers will be composed of can rows having therein the same number of cans.

63. Apparatus as defined in claim 41, in which the shaft carried platform descent controlling stops are so spaced as to drop the platform through layer depth steps incidental to the arranging of successive can layers, and then a longer step drop after the laying of the last layer so as to position the package complement of cans for being discharged from the platform, means also being included for assuring that when an odd number of layers is arranged on the platform the lowermost and uppermost layers will be composed of can rows having therein the same number of cans, said last-named means including a phasing switch connected in the circuit controlling oscillation of the stop shaft and operable on the last long drop of the platform to bring about a turning of the shaft to the position it occupied during the laying of the first and last laid layers of the last arranged bag complement of cans.

64. In apparatus of the character described, means providing a packaging station, means for presenting a package complement of cans at said station with the can axes arranged in generally horizontal position to receive a tubular wrapper thereabout with marginal edge portions extending beyond each end of said package complement of cans, means providing a final sealing station, a package receiver at said sealing station, and means including fixed guide trackways having horizontal guide portions and upright guide portions and curved portions

joining said horizontal and upright portions, and rollers carried by the package receiver and engaging in said trackways for controlling the position of said receiver to receive a package of cans in generally horizontal position after having one end thereof sealed at the packaging station and then turn said package into an upright position in which the other unsealed end thereof can be sealed with facility.

65. Apparatus as defined in claim 64, in which the receiver is U-shaped in vertical cross section when in the generally horizontal package receiving position and has an open end directed toward the packaging station, and a closed end directed away from said packaging station.

66. Apparatus as defined in claim 64, in which the receiver is U-shaped in vertical cross section when in the generally horizontal package receiving position and has an open end directed toward the packaging station, and a closed end directed away from said packaging station and composed of traversing anti-friction rollers forming a bottom over which a sealed package can be moved with facility when the receiver is placed to present the package in upright position.

67. Apparatus as defined in claim 64, in which the means for controlling the position of the receiver includes manually actuated devices for bringing about movement of the receiver to its generally horizontal package receiving position and devices automatically operable as a package is received in the receiver to bring about a movement of the receiver to the upright package presentation position.

68. Apparatus as defined in claim 64, in which there are included means for guiding movement of the receiver between an elevated generally horizontal position in which it receives a package and a lowered position in which it places the package in upright position for final sealing, and wherein the position controlling means includes cylinder and piston means effective to move the receiver to its elevated position and for controlling lowering movement of the receiver by gravity action after a package has been deposited therein.

69. Apparatus as defined in claim 64, in which there are included means for guiding movement of the receiver between an elevated generally horizontal position in which it receives a package and a lowered position in which it places the package in upright position for final sealing, and wherein the position controlling means includes cylinder and piston means effective to move the receiver to its elevated position and for controlling lowering movement of the receiver by gravity action after a package has been deposited therein, there being also included reciprocable ram means for pushing packages into the receiver while in its generally horizontal position, and control valve means manually operable to cause the cylinder and piston means to move the receiver to its elevated position, and automatically operable by ram movement to permit the receiver to gravitate to its lowered position with the lowering movement initiated by the pushing of a package into the receiver.

70. Apparatus as defined in claim 64, in which there are included means for guiding movement of the receiver between an elevated generally horizontal position in which it receives a package and a lowered position in which it places the package in upright position for final sealing, and wherein the position controlling means includes cylinder and piston means effective to move the receiver to its elevated position and for controlling lowering movement of the receiver by gravity action after a package has been deposited therein, and valve means for choking escape of air from the cylinder as the receiver is being moved to its elevated position to cushion said movement and also effective to trap air in the cylinder as the receiver is reaching its elevated position so that subsequent expansion of the trapped air as the lowering movement of the receiver is started will aid said lowering movement.

71. Apparatus as defined in claim 64, in which there

are included means for guiding movement of the receiver between an elevated generally horizontal position in which it receives a package and a lowered position in which it places the package in upright position for final sealing, said guiding means including portions effective to cause the receiver to move horizontally a limited distance as its lowering movement is initiated so as to clear the packaging station without fouling the marginal edge extension of the wrapper at the unsealed end of the package.

72. Apparatus as defined in claim 64, in which there are included means for guiding movement of the receiver between an elevated generally horizontal position in which it receives a package and a lowered position in which it places the package in upright position for final sealing, there being also included reciprocable ram means for pushing packages into the receiver while in its generally horizontal position, and means for imparting four-way movement to the ram means to project it horizontally from the packaging station to the receiving station, then upwardly at the receiving station, then retract it in elevated position to the packaging station and then lower it at the packaging station, said guiding means including portions effective to tilt the receiver slightly as the package is pushed thereinto to clear the marginal edge portions of the wrapper at the unsealed end of the package so that they will not be fouled by the ram as it is elevated at the sealing station.

73. Apparatus as defined in claim 64, in which there are included means for guiding movement of the receiver between an elevated generally horizontal position in which it receives a package and a lowered position in which it places the package in upright position for final sealing, there being also included reciprocable ram means for pushing packages into the receiver while in its generally horizontal position, and means for imparting four-way movement to the ram means to project it horizontally from the packaging station to the receiving station, then upwardly at the receiving station, then retract it in elevated position to the packaging station and then lower it at the packaging station, said guiding means including portions effective to tilt the receiver slightly in a direction for causing gravity to act on the cans in the trailing unsealed end of the package in a manner assuring against falling of said cans out of said package end as the movement of the receiver toward its lowered position is continued.

74. In apparatus of the character described, a can layer supporting platform, means for feeding individual layers of cans onto the platform, means for lowering the platform step-by-step to receive the can layers and arrange them in superposed relation, means for elevating the platform to its initial layer receiving position after a package complement of cans has been arranged thereon and discharged therefrom, a reciprocable ram for pushing a package complement of cans off the platform at the lower limit of its travel, and means for controlling the operation of the platform lowering and elevating means and the ram through a manually initiated automatically terminated cycle.

75. Apparatus as defined in claim 74, wherein there is included manually operable means for taking over the control of the lowering of the platform at any stage of the platform moving cycle.

76. Apparatus as defined in claim 74, wherein the platform lowering means comprises a stop member movable with the platform and vertically spaced platform level control stops engageable by the platform carried stop member and successively removable for permitting the platform to fall accurately determined step distances by gravity action, and wherein there is included manually operable means for controlling the removal of said control stops at any stage of the platform moving cycle.

77. Apparatus as defined in claim 74, wherein the platform lowering means comprises a stop member mov-

able with the platform, an upright shaft having vertically spaced radially projecting stops thereon engageable by the platform carried stop member, and means for moving the shaft about its axis to selectively present said stops, and wherein there is included independent manually operable means for bringing about movements of the shaft about its axis to effect a step-by-step lowering of the platform at any stage of the platform moving cycle.

78. In apparatus of the character described, means for rolling multiple can rows on their sides into horizontal parallel row relation to form can layers, a platform on which to receive an initially laid layer of cans, means for lowering the platform successive step distances to permit the rolling thereonto of successive can layers, thereby to arrange the can layers to constitute a package complement of cans, means providing a packaging station, a reciprocable ram, means for operating the ram each time the platform reaches its fully lowered position to push the arranged package complement of cans therefrom and place the same at said packaging station, another ram and means for mounting the same for vertical and horizontal reciprocation, and control means for said other ram for causing the same to move with the first ram during the movement of the cans to the packaging station, with the package complement of cans engaged at its ends between and held under control by the rams, then move upwardly away from the cans, then at a high level back toward the platform to an intermediate stop position, then downwardly, then toward the first ram to engage a newly arranged package complement of cans before the same on the platform, latch means for intercepting said other ram at said intermediate stop position, and means for releasing said latch means to permit said other ram to move into engagement with the cans only if the platform has been fully lowered.

79. Apparatus as defined in claim 78, in which there is provided means forming a sealing station, and still another ram and means for mounting the same for vertical and horizontal reciprocation, and means for controlling said last-named ram to first lower it into position behind a package at the packaging station, then move it horizontally to push the package to the sealing station, then elevate it, and then retract it horizontally to its initial elevated position, said control means including devices preventing lowering of the latch intercepted ram unless it is in its latch intercepted intermediate stop position and the package pushing ram has been moved the maximum distance toward the sealing station.

80. The herein described method of arranging cans for packaging which comprises rolling multiple rows of cans on their sides onto a horizontal support to form a layer of cans, lowering the support successive step distances each approximately the diameter of a can, and after each said step lowering of the support, rolling another layer of cans directly onto and over the last laid layer of cans, and stopping the inrolling of alternately laid can layers in position for placing them in staggered and nested layer relation to the other layers, said method also including the steps of placing tier sheets uprightly in parallel spaced relation on the platform so that cans in individual rows will roll into position between two tier sheets and the tier sheets and can layers will move down step-by-step, forming a tubular paper enclosure snugly about the package complement of cans with marginal portions of the paper projecting at each end beyond the cans of the package complement, and then folding in and sealing said projecting marginal portions against the endmost tier sheets to complete the package.

81. The herein described method of arranging cans for packaging which comprises rolling multiple rows of cans on their sides onto a horizontal support to form a layer of cans, lowering the support successive step distances each approximately the diameter of a can, and

after each said step lowering of the support, rolling another layer of cans directly onto and over the last laid layer of cans, and stopping the inrolling of alternately laid can layers in position for placing them in staggered and nested layer relation to the other layers, said method also including the steps of placing tier sheets uprightly in parallel spaced relation on the platform so that cans in individual rows will roll into position between two tier sheets and the tier sheets and can layers will move down step-by-step, applying pressure at ends of the package complement of cans to compact the same, forming a tubular paper enclosure snugly about the package complement of cans while the endwise pressure is being held thereon, and folding in and sealing the projecting marginal portions of the paper against the endmost tier sheets at at least one end of the package to form a sealed end closure.

82. The herein described method of arranging cans for packaging which comprises rolling multiple rows of cans on their sides onto a horizontal support to form a layer of cans, lowering the support successive step distances each approximately the diameter of a can, and after each said step lowering of the support, rolling another layer of cans directly onto and over the last laid layer of cans, and stopping the inrolling of alternately laid can layers in position for placing them in staggered and nested layer relation to the other layers, said method also including the steps of placing tier sheets uprightly in parallel spaced relation on the platform so that cans in individual rows will roll into position between two tier sheets and the tier sheets and can layers will move down step-by-step, and while holding the package complement of cans in position with the can axes generally horizontal applying pressure at the ends thereof to compact the same and forming a tubular paper enclosure snugly about the package complement of cans and folding in and sealing the projecting marginal portions of the paper against the endmost tier sheet at one end of the package to form a sealed bottom, then turning the package to place said bottom downwardly and folding in and sealing the remaining upwardly directed marginal portions of the paper against the other endmost tier sheet to complete the package.

83. In apparatus of the character described, inclined gravity rollways over which to roll multiple can rows on their sides into horizontal parallel row relation to form can layers, a platform on which to receive an initially laid layer of cans, means for lowering the platform successive step distances to permit the rolling in of successive can layers directly onto and over previously laid can layers, and means for placing tier sheets uprightly in parallel spaced relation on the platform and in position for having each row of the cans making up a layer roll into position between two tier sheets, with the platform, tier sheets and the successively laid can layers movable downwardly in unison.
